UNITED STATES PATENT OFFICE

2,224,517

TELEPHONE SYSTEM

Frank Kessler, Villa Park, Ill., assignor to Associated Electric Laboratories, Inc., Chicago, Ill., a corporation of Delaware

Application April 21, 1939, Serial No. 269,161

45 Claims. (Cl. 179—27)

The present invention relates to telephone systems and, more particularly, to automatic telephone systems wherein a portion of the subscribers' lines are of the multiparty type.

5 As explained in Patent No. 1,267,113—Powell, granted May 21, 1918, in telephone systems of the character indicated, when one or more of the substations associated with a multiparty subscriber's line is taken out of service or disconnected from 10 the line, it is desirable to provide an arrangement whereby calls intended for the disconnected substation are routed to an operator's position so that the calling subscribers can be informed that the called substation is no longer in service. Intercepting service of this character is also desirable in other instances when calls to substations 15 actually in service are to be intercepted. An improved arrangement for providing call intercepting service of the character just mentioned is disclosed in the copending application of Carl O. Wright, Serial No. 267,956, filed April 15, 1939. The system disclosed in this copending application utilizes ringing apparatus of the harmonic type which is so arranged that the ringing voltages of different frequencies and individually corresponding to the substations of the multiparty lines of the system are transmitted to the groups of connector switches of the system successively and during different ringing intervals. In accordance with the invention therein disclosed, 20 there is provided a relay which is controlled by the ringing apparatus and is arranged to operate only during one of the intervals of each ringing cycle. This relay, in cooperation with a second relay connected to be energized by ringing current of any frequency projected over the line arranged for call interception, functions to initiate the operation of apparatus for routing a connection from the calling line to the intercepting operator's position. More particularly, the first-mentioned relay corresponds only to the substation 25 with respect to which calls are to be intercepted and operates only during those ringing intervals when ringing current for signaling this substation would normally be projected over the associated line. Accordingly, by arranging the call-forwarding apparatus to operate only when the two relays are both operated, only calls intended for the substation corresponding to the 30 first-mentioned relay are routed to the call intercepting operator's position. While this arrangement is perfectly satisfactory in operation when incorporated in a system designed for the well-known directory method of establishing reverting call connections between the substations associ-

ated with the multiparty lines, it is not applicable for use in a system wherein reverting call switches are provided for the purpose of controlling the ringing operations required incident to the establishment of reverting call connections. Moreover, the arrangement, like other prior arrangements of the same general character, is connected to be used only for the purpose of intercepting calls intended for substations which have been or are associated with the multiparty lines of the 10 system. Another desirable service frequently provided in automatic telephone systems is that of routing to an operator's position calls which have inadvertently been extended to the inactive contacts forming a dead level of contacts embodied in one of the selector switches of the system. In the usual arrangement, these two services are entirely divorced, separate and independent apparatus being provided for rendering the services of different types. 20

It is an object of the present invention, therefore, to provide, in an automatic telephone system including one or more subscribers' lines of the multiparty type, improved apparatus arranged to perform the dual functions of intercepting and routing to an operator's position certain predetermined calls routed to the multiparty lines of the system and calls which have inadvertently been extended to the inactive contacts of one of the selector switches embodied in the sys- 30 tem. 25

It is another object of the present invention to provide, in a automatic telephone system including one or more multiparty lines and arranged to utilize reverting call switches in completing reverting call connections, improved apparatus of simple and economical arrangement which operates in a new and improved manner to intercept certain calls routed to the multiparty lines and automatically to extend the intercepted calls to 40 an operator's position. 35

It is a further object of the invention to provide, in a system of the character indicated, improved apparatus for controlling the ringing operations performed incident to the completion of 45 reverting call connections.

The invention is illustrated in its embodiment in an automatic telephone system which includes an operator's position, a plurality of lines, one or more of which is of the multiparty type, and automatic switching apparatus for setting up connections between the lines. In order clearly to indicate the utility of the invention, one of the selector switches embodied in the system is assumed to have a dead level of bank contacts, that 50 55

is, a contact level which includes inactive contacts not connected to trunk lines outgoing from the switch. In accordance with the present invention, there is provided apparatus responsive to 5 a call routed from a calling one of the subscribers' lines through the automatic switching apparatus to the first set of inactive contacts of the above-mentioned dead contact level for extending a connection from the calling line to the operator's position, together with means responsive to 10 a call routed from a calling one of the subscribers' lines through the automatic switching apparatus to the multiparty line and intended for one of the substations normally associated with 15 the multiparty line for extending to the same operator's position a connection from the calling line. More particularly, the operator's position has associated therewith line connecting apparatus through which the calls of both types are 20 routed. This line connecting apparatus is so arranged that it is only capable of handling one call at a time, lockout means being provided for preventing the operation of the substation call intercepting apparatus when a call is routed through 25 the apparatus provided for dead level call interception and vice versa.

The automatic switching apparatus embodied in the system further comprises a reverting call switch which, in conjunction with the harmonic 30 ringing apparatus of the system, functions to control the application of ringing voltage to the multiparty lines incident to the completion of reverting call connections. This reverting call switch is arranged to impress upon 35 any one of the multiparty lines having a reverting call initiated thereon ringing voltages of the frequencies respectively corresponding to the calling and called substations associated with the line. There is also provided, in association with 40 the ringing apparatus of the system, a plurality of sets of relays which individually correspond to the ringing intervals of each ringing cycle. Each of the sets of relays is operative to divide 45 each corresponding ringing interval into two periods and the arrangement is such that ringing voltage is impressed upon any one of the multiparty lines, having a reverting call initiated thereon, through the reverting call switch only during the second period of each ringing interval. 50 The respective first periods of the ringing intervals being reserved for the control of the line connecting apparatus to intercept certain calls routed to the multiparty lines. More particularly, each set of relays has associated therewith 55 a control device which is operative during the first period of each corresponding ringing interval. Each of the control devices may be arranged to initiate the operation of the line connecting apparatus to extend connections from 60 called ones of the multiparty lines to the intercepting operator's position when the selected ringing interval, during which ringing current is projected over a selected called line, overlaps the period during which the control device 65 responding to the selected interval is operated.

Further features of the invention pertain to the particular arrangement of the apparatus whereby the above and additional operating features are attained.

70 The novel features believed to be characteristic of the invention are set forth with particularity in the appended claims. The invention, both as to its organization and method of operation, together with further objects and advantages 75 thereof, will best be understood by reference to

the specification taken in connection with the accompanying drawings, in which Figs. 1 to 6, inclusive, when combined in the manner shown in Fig. 7, illustrate an automatic telephone system having embodied therein the features of 5 the invention briefly described above. More particularly, Fig. 1 illustrates in schematic form certain of the lines and certain of the automatic switching apparatus embodied in the system; Fig. 2 illustrates the intercepting operator's position and the line connecting apparatus associated therewith; Fig. 3 illustrates the harmonic ringing apparatus embodied in the system; Fig. 4 illustrates a reverting call switch which is utilized in the completion of reverting call connections; Fig. 5 illustrates the apparatus for routing a connection from an inactive set of bank contacts of one of the selector switches embodied in the system through the line connecting apparatus of Fig. 2 to the intercepting 20 operator's position; and Fig. 6 illustrates the equipment for controlling the line connecting apparatus of Fig. 2 to intercept certain of the calls routed to the multiparty lines of the system.

In brief, the system comprises an exchange, 25 a plurality of single party subscribers' lines, one of which is indicated at 10, extending to the exchange, and a plurality of subscriber-controlled automatic switches including line switches indicated at 15 and 20, respectively, a selector switch 30 25, and a connector switch 30, for setting up connections between the various subscribers' lines. The exchange housing the automatic switching equipment also has extending thereto a plurality of multiparty lines, one of which is 35 indicated at 11 as terminating in the line switch 15 and the bank contacts of the connector switch 30. This line has associated therewith a plurality of substations B, C, and D which individually include signal devices in the form of 40 harmonic ringers 12, 13 and 14 bridged across the conductors of the line 11 in series with the condensers 16, 17 and 18, respectively. The harmonic ringers bridged across the line 11 at the various substations are tuned to respond to ring- 45 ing currents of different frequencies so that any desired one of the substations may be signaled to the exclusion of the others by projecting ringing current of the proper frequency over the line 11. The end of the line 10 remote from the 50 exchange terminates at a subscriber's substation A of the usual common battery type. The line switches 15 and 20 and the other similar switches of the system are non-numerical switches in the sense that they are ineffective to perform any 55 line selecting functions other than those of selecting idle ones of the selector switches. The selector and connector switches, on the other hand, are commonly known as numerical switches in that they are operative to perform 60 particular line selecting functions in response to impulses transmitted thereto. It will be understood that a plurality of switches of each type, namely, a plurality of line switches, a plurality of selector switches, and a plurality of connector 65 switches, are provided in the system for performing the usual line switching functions. The switches of each type are respectively arranged in groups and, in accordance with universally followed practice, the number of switches in each 70 group is determined by the maximum volume of traffic the particular switch group is required to handle. Further in accordance with conventional practice, each of the subscribers' lines is multi-timed between the corresponding bank con- 75

tacts of a group of connector switches, whereby a plurality of such switches are rendered available for setting up connections between each line and every other line of the system. The line switches, on the other hand, are individually associated with the respective subscribers' lines.

Each of the line switches 15, 20, etc., is preferably of the well-known rotary type, of which several commercial embodiments are available. 10 Each of the selector and connector switches is preferably of the well-known Strowger type having embodied therein a wiper carriage structure adapted to be translated vertically to bring the wipers thereof to a position opposite a particular level of bank contacts and then rotated to bring the wipers into engagement with a particular set of bank contacts in a selected level; vertical, rotary and release magnets; and control relays suitably connected and arranged to control the 20 energization of the various magnets and the line switching in accordance with the particular functions of the switch. Obviously, the particular arrangement of the control apparatus embodied in the switches of different type is different in each instance, depending upon the character of the switch.

In order more clearly to explain the operation of the circuits to which the invention pertains, a portion of the relay equipment embodied in the line switch 15 and the connector switch 30 has been shown in detail. More particularly, the equipment of the connector switch 30 comprises a slow-to-operate ringing control relay R100, a slow-acting ring cutoff relay R110, and a ringing 35 frequency selecting switch 120 of the well-known minor type. In brief, the switch 120 comprises a single set of bank contacts 121, a wiper 122, means comprising an operating magnet 123 for driving the wiper 122 over the contacts of the contact set 121, a release magnet 124 for causing the wiper 122 to be returned to its normal or home position, and a pair of off-normal springs 125 for controlling the operating circuit for the release magnet 124. The line switch 15 includes 40 a line relay R130 which is illustrated in the drawing in order to facilitate an explanation of certain of the circuits referred to hereinafter.

In order to explain the operation of the call intercepting apparatus to intercept calls inadvertently routed to a dead level of one of the selector switches embodied in the system, the selector switch 25 is illustrated as comprising a level of bank contacts, the contacts of which are not connected to lines outgoing from the switch 55 but are reserve contacts which may be used if traffic conditions are such as to require additional connector switches in the system. This level of dead contacts is indicated as comprising a first set of contacts 26, 27 and 28; these being connected by means of conductors 31, 32 and 33, forming a trunk 36, to the control equipment illustrated in Fig. 5.

The equipment provided in the line terminating exchange also comprises cyclically operating 65 ringing apparatus for delivering to the various connector switches ringing currents of five different frequencies. The arrangement of this apparatus is such that the ringing currents of different frequencies are delivered to the different 70 groups of connector switches during different intervals of each ringing cycle. For example, the arrangement may be such that during the first ringing interval of each ringing cycle, ringing current of the frequency F1 is delivered to a first 75 group of connector switches, ringing current of

the second frequency F2 is delivered to a second group of the connector switches, ringing current of the third frequency F3 is delivered to a third group of the connector switches, ringing current of the fourth frequency F4 is delivered to a fourth group of connector switches, and ringing current of the fifth frequency F5 is delivered to a fifth group of connector switches; and during the second interval of each ringing cycle, ringing current of the first frequency is delivered to the 10 third group of connector switches, ringing current of the second frequency is delivered to the fourth group of connector switches, ringing current of the third frequency is delivered to the first group of connector switches, etc. With the 15 particular arrangement illustrated, ringing currents of the frequencies F1, F3, F5, F2 and F4 are successively delivered, in the order named, to the connector switches of the group including the switch 30, during different periods of each ringing 20 cycle. More particularly, the ringing apparatus is illustrated in Fig. 3 as comprising five motor driven alternating current generators 301 to 305, inclusive, having output current frequencies F1, F2, F3, F4 and F5, respectively. These generators are arranged to deliver ringing current by way of ringing current conductors to the various connector switches of the system. The ringing current conductors are arranged in groups respectively extending to the different groups of 30 connector switches. One such group of ringing current conductors is illustrated as comprising the conductors C306, C307, C308, C309 and C310, which are arranged to deliver ringing currents to the connector switches of the group including the 35 switch 30. To this end, these conductors are connected by way of the cable conductors of a cable 311 to the respective contacts of the contact set 121 embodied in the frequency selecting switch 120 of the connector switch 30. These 40 same conductors are multiplied in the corresponding bank contacts of the frequency selecting switches respectively embodied in the other connector switches of the group including the 45 switch 30. In a similar manner, the ringing current conductors of the bracketed group 312 are terminated in the bank contacts of the various 50 frequency selecting switches respectively embodied in the connector switches forming the second group. The remaining fifteen ringing current conductors are divided into three additional groups for serving three additional groups of connector switches.

For the purpose of connecting the indicated ringing current conductors to the generators 301 55 to 305, inclusive, there are provided five ringing relays R320, R330, R340, R350 and R360, and a ringing interrupter switch 370 of conventional arrangement. This ringing interrupter switch has extending thereto a start conductor C336 60 over which the start relay conventionally embodied in the switch is arranged to be energized in response to operation of any one of the connector switches of the system. The interrupter switch 370 also has extending thereto a pick-up conductor C337 by way of which the ringing relays of the various connector switches are controlled to control the application of ringing current of a selected frequency to a selected called line. The ringing interrupter switch 370 is arranged repeatedly to operate through identical 70 cycles. During each cycle of operation, the apparatus embodied in this switch functions to impress ground potential successively upon the conductors C326, C327, C328, C329 and C338 for 75

different intervals of substantially equal duration. As a result, the relays R320, R330, R340, R350 and R360 are energized and operate in succession, each thereof functioning, when operated, to connect its associated ringing current conductors to the five alternating current generators. Thus, during the first period of each ringing cycle, the relay R320 operates its armature RA321 to disconnect the ringing conductor C306 5 from ground and to connect this conductor to the ungrounded terminal of the alternating current generator 301. In a similar manner and at its armatures RA322 to RA325, inclusive, the relay R320 disconnects the four other associated ringing current conductors from ground and connects these conductors to the alternating current generators 302, 303, 304 and 305, respectively. Since the relay R320 is alone operated during the first interval of each ringing cycle, only the ringing current conductors associated with this relay are connected to the indicated alternating current generators during such intervals. During the second interval of each ringing cycle, the second ringing relay R330 operates its armature 10 RA331 to disconnect the ringing current conductor C308 from ground and to connect this conductor to the ungrounded terminal of the alternating current generator 303. In a similar manner, the other ringing current conductors associated with the second ringing relay R330 are disconnected from ground and connected to the corresponding alternating current generators during the second interval of each ringing cycle. At the beginning of the third interval of each ringing 15 cycle, when the relay R340 is operated, this relay, at its armature RA345, disconnects the ringing current conductor C310 from ground and connects this conductor to the ungrounded terminal of the alternating current generator 305. Similarly, the other ringing current conductors associated with the third ringing relay R340 are connected to the ungrounded terminals of their respective corresponding generators during the third interval of each ringing cycle. During the 20 fourth interval of each ringing cycle, when the fourth ringing relay R350 is operated, the armature RA352 is operated to disconnect the ringing current conductor C307 from ground and to connect this conductor to the ungrounded terminal of the generator 302. In a similar manner, the other ringing current conductors associated with the fourth ringing relay are disconnected from ground and connected to their respective corresponding generators during the fourth interval 25 of each cycle of operation of the interrupter switch 370. Finally, the ringing relay R360 operates during the fifth ringing interval of each ringing cycle to disconnect, at its armature RA364, the ringing current conductor C309 from ground and to connect this conductor to the ungrounded terminal of the generator 304. Similarly, the other ringing current conductors associated with the fifth ringing relay R360 are disconnected from ground and connected to the ungrounded terminals of their respective corresponding generators during the fifth interval 30 of each ringing cycle. The arrangement of the interrupter switch 370 is such that ground potential is impressed upon the pick-up conductor C337 at the beginning of each cycle of operation thereof. From the foregoing explanation, it will be apparent that the ungrounded terminals of the generators 301, 303, 305, 302 and 304 are connected to the respective ringing current conductors C306, C308, C310, C307 and C309 during 35

succeeding ringing intervals of each ringing cycle.

The system further comprises an operator's position 200 to which certain calls may automatically be extended through operation of the 5 improved line connecting apparatus illustrated in Fig. 2. The equipment provided at the operator's position comprises an operator's telephone set 202 of any conventional arrangement, an answer key 201, a hold key 203, an incoming 10 call signal lamp 204, and a signal lamp 205 for indicating those intervals when the key 203 is operated to its off-normal position. Each of the keys 201 and 203 is of the well-known locking type such that when operated to its off-normal 15 position it remains in the off-normal position until manually restored to normal.

As indicated in the introductory portion of the specification, the system is arranged to utilize reverting call switches in completing reverting 20 call connections between substations associated with the same lines. One switch provided for this purpose is illustrated in Fig. 4 as comprising a pair of ringing frequency selecting switches 400 and 410, each of which is of the well-known 25 minor type. The minor switch 400 is operative in response to a second series of impulses transmitted to the reverting call switch to select the frequency of the ringing current corresponding to the substation at which a reverting call originates. In brief, this switch comprises two sets of bank contacts 401 and 402, wipers 403 and 404 respectively associated with the two contact sets, means comprising a rotary magnet 405 and a ratchet and pawl mechanism, not shown, for operating the enumerated wipers to a desired off-normal position to select a desired ringing frequency, a release magnet 406 for restoring the wipers to normal, and a pair of off-normal springs 407 which are moved into engagement when the 30 wipers 403 and 404 are operated to their respective first off-normal positions. The switch 410 is provided for the purpose of selecting, in response to a first series of impulses transmitted to the reverting call switch, the ringing current of the 35 particular frequency corresponding to a desired called substation. This second switch is of identical construction with the switch 400 and comprises two contact sets 411 and 412, wipers 413 and 414 individually associated with the contact 40 sets, a rotary magnet 415 for driving the wipers over the contacts of their respective associated sets, a release magnet 416, and a pair of off-normal springs 417. For the purpose of controlling the two minor switches 400 and 410 and of controlling the ringing operations performed incident to the completion of reverting call connections, there is also embodied in the reverting call switch a plurality of control relays. These relays include a line relay R420, a slow-acting hold relay R435, a pair of digit transfer relays R450 and R440 arranged to be controlled by a slow-to-release impulse responsive relay R445, a line switching relay R420, a pair of ringing relays R465 and R470, and a pair of ring cutoff and release relays 50 R455 and R460. 55

Neglecting for the present the details of the apparatus illustrated in Figs. 2, 5 and 6, provided for the purpose of routing calls to the operator's position 200, the system as described above is, in 60 general, entirely conventional in form and its operation is well understood in the art. In brief, when a subscriber, such, for example, as the subscriber at the telephone A lifts his receiver from its hook to initiate a call intended for a 65 70 75

second subscriber's telephone, such, for example, as the telephone B, a loop circuit is completed for initiating the operation of the line switch 20 to select a trunk line leading to an idle selector switch. Assuming, for example, that the selector switch 25 is selected by the line switch 20, when the trunk line leading to this selector switch is seized, the calling loop circuit is extended to this selector switch and the switch is conditioned to respond to the first series of impulses dialed at the calling substation. With the selector switch 25 in this condition, the usual dial tone signal is returned over the established loop circuit to the calling subscriber to indicate that the dialing operation may be started. When the first digit is dialed at the calling substation, the switch 25 elevates its wipers to a position opposite the level of bank contacts terminating the trunks leading to the connector switches having access to the called line 11. Following this operation and during the interdigit pause between the first and second digits, the wipers of the switch 25 are automatically stepped over the contacts of the selected level until a trunk line leading to an idle connector switch of the selected group is found. Assuming that the connector switch 30 is the first available idle connector switch in the selected group, when the wipers of the selector switch 25 are stepped into engagement with the contacts terminating the trunk line extending to this connector switch, the subscriber's loop circuit is extended to the switch 30, thereby to cause this connector switch to be conditioned to respond to the second series of impulses dialed at the calling substation. When the connector switch 30 is seized in the manner just described, certain of the control relays embodied therein, and more particularly the line and hold relays, operate to complete a path for impressing ground potential upon the start conductor C336 extending to the ringing interrupter switch 370, thereby to initiate the operation of the interrupter switch in the event it is not already in operation. When operation of the interrupter switch 370 is initiated, the relays R320, R330, R340, R350 and R360 function, in the manner previously explained, successively to connect the conductors C306 to C310, inclusive, to the generators 301 to 305, inclusive, during the different intervals of each ringing cycle. When the second digit is dialed at the calling substation the wipers of the connector switch 30 are stepped vertically to a position opposite the level of bank contacts at which are terminated the lines of the ten line subgroup including the called line 11. Following this digit and during the interdigit pause between the second and third digits, the connector switch is conditioned to rotate its wipers step by step in accordance with the impulses of the third digit of the directory number designating the called substation. When this third digit is dialed, the wipers of the switch 30 are operated into engagement with the set of bank contacts terminating the called line 11. During the interdigit pause between the third and fourth digits, circuits are prepared for energizing the operating magnet 123 of the frequency selecting switch 120 in accordance with the impulses of the fourth and final digit. The indicated operating magnet responds to the impulses of the fourth digit by operating the wiper 122 into engagement with the contact of the contact set 121 having impressed thereon ringing voltage of the particular frequency required to operate the harmonic ringer 12 provided at the

called substation B. If it be assumed, for example, that the ringer 12 is constructed to respond only to ringing current of the frequency F2, the fourth digit dialed at the calling substation will comprise two impulses so that at 5 the conclusion thereof the wiper 122 will be left standing in engagement with the contact terminating the ringing conductor C307. During the operation of the switch 120 and when the wiper 122 is stepped to its first off-normal position, the off-normal springs 125 are closed to prepare an incomplete circuit for energizing the release magnet 124, this circuit being held open until the switch 30 is released. 10

In accordance with conventional practice, suitable provisions are made for testing the selected called line 11 to determine the idle or busy condition thereof, for returning the usual busy tone signal over the established loop circuit to the calling subscriber in the event the called line is busy, 15 and for projecting ringing current of the selected frequency over the called line in the event this line is idle at the time it is selected. Assuming that the called line is idle, a circuit is prepared, through operation of certain of the relays embodied in the connector switch 30, for energizing the lower winding of the slow-to-operate ringing control relay R100. This circuit is thereafter completed at the beginning of the next cycle of operation of the ringing interrupter switch 370 20 when ground potential is impressed upon the pick-up conductor C337, and may be partially traced as extending from ground by way of C337, the lower winding of R100, the test wiper of the connector switch 30, the private conductor of the 25 line 11, and through the winding of the cut-off relay conventionally embodied in the line switch 15 to battery. When this circuit is completed, the cut-off relay embodied in the line switch 15 partially operates to disconnect the windings of 30 the line relay R130 from the conductors 11a and 11b of the called line 11, thereby to clear this line of the shunt impedance represented by these windings. Completion of the circuit just traced also results in the energization and operation of 35 the ringing control relay R100. This relay, upon operating, completes, at the "X" contacts associated with RA102, a holding circuit for itself, this holding circuit having been previously prepared through operation of certain of the other 40 relays, not shown, embodied in the connector switch 30. At its armatures RA101 and RA103, the relay R100 completes a circuit for projecting 45 ringing current of the selected frequency over the conductors of the line 11. In the present 50 case, the circuit traversed by the ringing current may be traced as extending from the ungrounded terminal of the generator 302 by way of RA352, C307, the second contact of the set 121, the wiper 122, RA113, RA103, the conductor 11b, the 55 windings of the ringer 12, the condenser 16, the conductor 11a, RA101, RA111, the upper winding of R110 and the exchange battery to the 60 grounded terminal of the generator 302. Portions of this current are obviously shunted 65 through the harmonic ringers respectively provided at the other substations associated with the line 11. The ringer 12, however, is the only ringer which responds to current of the particular frequency developed by the generator 302. 70 Operation of this ringer serves to signal the called subscriber that he is being called. A portion of the ringing current is also shunted, in the usual manner, over the calling loop circuit to energize the receiver provided at the calling substation. 75

thereby to indicate to the calling subscriber that the called substation is being signaled. It will be apparent from the foregoing explanation with reference to the ringing apparatus shown in Fig. 3 that ringing current of the frequency F_2 is only intermittently projected over the line 11 to cause operation of the ringer 12 . More particularly, ringing current is projected over this line only during the fourth interval of each ringing cycle.

The desired conversational circuit between the calling and called substations is fully completed when the call is answered at the called substation B . More particularly, when the receiver at this substation is removed from its supporting hook, a direct current conductive bridge is connected across the conductors 11_a and 11_b of the line 11 to complete a circuit for energizing the upper winding of the slow-acting ring cut-off relay $R110$. This circuit may be traced as extending from ground by way of $RA352$, $C307$, the second contact of the set 121 , the wiper 122 , $RA113$, $RA103$, the conductor 11_b , the bridge across the conductors 11_b and 11_a , the conductor 11_a , $RA101$, $RA111$, and the upper winding of $R110$ to battery. When its upper winding is energized over this circuit, the relay $R110$ operates to close the "X" contacts associated with $RA112$, thereby to complete a prepared holding circuit for itself. Thereafter, the relay $R110$, at its armatures $RA111$ and $RA113$, and their respective associated resting contacts, opens two points in its operating circuit and two points in the above-traced circuit for projecting ringing current over the line 11 . At these same armatures and their respective associated working contacts, the relay $R110$ completes the desired conversational circuit between the calling and called substations. When the relay $R110$ operates it also functions to open the path, not shown, by way of which ring-back tone current is projected over the calling loop circuit, thereby to terminate the ring-back tone signal in the usual manner.

Preferably, the control relays of the connector switch 30 are so arranged that the release of the operated switch train is under the control of the calling subscriber at the substation A . With such an arrangement, when the connection is cleared out at the calling substation, the loop circuit extending through to the operated connector switch 30 is interrupted to cause the release of the line and hold relays conventionally embodied in this switch in the usual manner. When these relays restore, the line and selector switches 20 and 25 , respectively, are released and the control apparatus embodied in the connector switch 30 is restored to normal, all in a manner well understood in the art. During the release of the control apparatus embodied in the connector switch 30 , the previously traced holding circuits for the two relays $R110$ and $R100$ are interrupted, causing these relays to restore. Also, ground potential is removed from the private conductor of the called line 11 , whereby the cut-off relay embodied in the line switch 15 is released to reconnect the windings of the line relay $R130$ to the conductors 11_a and 11_b of the line 11 . When ground potential is removed from the private conductor of the line 11 , battery potential is impressed upon this conductor through the windings of the cut-off relay embodied in the line switch 15 , thereby to mark the line as idle in the bank contacts of the connector switches having access thereto. When the line and hold relays embodied in the connector

switch 30 restore, a circuit is also completed for energizing the release magnet of the Strowger mechanism embodied in this switch, thereby to cause the wiper carriage structure of this mechanism to be restored to rotary and vertical normal. Similarly, a circuit is completed by way of the off-normal springs 125 for energizing the release magnet 124 of the frequency selecting switch 120 , whereby the wiper 122 of this switch is restored to normal. When this wiper attains its normal position, the off-normal springs 125 are opened to interrupt the operating circuit for the release magnet 124 . Thus, the switch train is fully released.

Referring now more particularly to the apparatus illustrated in Figs. 2, 5 and 6, for extending connections to the operator's position 200 , the line connecting apparatus associated with this operator's position is illustrated in Fig. 2 as comprising a plurality of line relays, one of which is indicated at $R220$, individually associated with the multi-party subscribers' lines with respect to which calls are to be intercepted. This apparatus also comprises a pair of cut-off relays $R240$ and $R270$, together with three control relays $R230$, $R250$ and $R260$, which function in the manner pointed out hereinafter to control the signal lamp 204 and the indicated cutoff and line relays. A slow-to-operate start relay $R290$ may also be included in this apparatus if required.

The apparatus illustrated in Fig. 5 and provided for the purpose of routing connections from dead or inactive contacts of the selector switches to the line connecting apparatus shown in Fig. 2 consists of a group of relays including a line relay $R500$, a slow-acting hold relay $R510$, a line switching relay $R540$, a slow-to-operate signal lamp control relay $R550$, and a cutoff relay $R530$. As indicated, this apparatus is connected by way of the trunk line 36 to the first set of contacts in the dead level of bank contacts embodied in the selector switch 25 .

The ringing control apparatus illustrated in Fig. 6 is provided for the purpose of preventing inadvertent operation of the line relays associated with the multi-party lines arranged for call interception when reverting calls are initiated on these lines. More particularly, this apparatus functions to divide each ringing interval of each ringing cycle defined by operation of the interrupter switch 370 into two periods; the first period of each interval being allotted to control of the line relays associated with the multiparty lines and embodied in the apparatus illustrated in Fig. 2. The second and predominant period of each ringing interval is allotted to control of the ringing relays $R465$ and $R470$ embodied in the reverting call switch illustrated in Fig. 4. With the particular arrangement illustrated in Fig. 6, each ringing interval of one second duration is divided into two parts, the first period being of approximately one-quarter of a second duration and the second period being of approximately three-quarters of a second duration. Specifically, the apparatus shown in Fig. 6 comprises a plurality of sets of relays 761 to 765 , inclusive, which individually correspond to the five ringing intervals of each ringing cycle and individually function to split each of the corresponding intervals into the two periods mentioned above. The enumerated sets of relays are arranged to be controlled by the interrupter switch 370 over the conductors $C326$, $C327$, $C328$, $C329$ and $C330$ and have individually associated therewith master relays $R600$, $R605$, $R610$, $R615$ 70

and R620. More particularly, the relay set 761 comprises two slow-acting relays R625 and R630 and a third fast-acting relay R640, which relays are arranged to cause the operation of the associated master relay R600 during the first period of each corresponding ringing interval and to impress ground potential upon the ringing control conductor C645 during the second period of each corresponding ringing interval. In a similar manner the second set of relays 762 comprises a sensitive relay R660 and two slow-acting relays R650 and R655, which relays function to control the operation of the associated master relay R605 and the application of ground potential to the second ringing control conductor C646. The third set of relays 763 similarly includes a sensitive relay R680 and a pair of slow-acting relays R670 and R675, which relays function to control the master relay R610 and the application of ground potential to the first ringing control conductor C645. The fourth set of relays 764 includes a pair of slow-acting relays R680 and R695 and a sensitive relay R700, which three relays are arranged to control the master relay R615 and the application of ground potential to the second ringing control lead C646. Finally, the fifth set of relays 765 comprises a sensitive relay R720 and a pair of slow-acting relays R710 and R715, which three relays are arranged to control the associated master relay R620 and the application of ground potential to the first ringing control conductor C645. This fifth set of relays is also arranged to control a pair of additional relays R730 and R740 which function to reverse the connections of the ringing conductors C747 and C748 to the ringing control conductors C645 and C646 at the end of each cycle of operation of the interrupter switch 370. The two ringing control conductors C747 and C748 are multiplied to the corresponding relay contacts of each of the reverting call switches embodied in the system. For the purpose of operatively associating the relay sets 761 to 765, inclusive, with the interrupter switch 370, there is provided a connect relay R150. The above-enumerated master relays are arranged in the manner more particularly described hereinafter directly to control the line relays, such, for example, as the relay R220, individually associated with the multiparty lines and provided for the purpose of connecting these lines to the apparatus shown in Fig. 2. In order to prevent any one of these line relays from responding to a transient voltage impressed upon the associated line due to a lightning surge or the like, there is provided a slow-to-operate relay R683 which functions momentarily to delay the complete operation of an energized one of the indicated line relays following its initial energization.

Referring now more particularly to the operation of the apparatus illustrated in Fig. 6, when ground potential is impressed upon the start conductor C336 extending to the interrupter switch 370 to initiate the operation of this interrupter switch in the manner previously explained, a circuit is completed for energizing the relay R630 of the first relay set 761, this circuit extending by way of the grounded conductor C336, RA751 and the winding of R630 to battery. When energized over this circuit, the relay R630 operates to complete, at RA631, an obvious circuit for energizing the associated slow-acting relay R625. The relay R625, upon operating, opens, at RA628, a point in the path, traced hereinafter, for impressing ground potential upon the ringing control conductor C645. At RA627, the relay R625 prepares a circuit, traced hereinafter, for energizing the relay R600. At RA628, the relay R625 completes a circuit for energizing the connect relay R150, this circuit extending by way of the grounded start conductor C336, RA751, RA626, RA727, RA643 and the winding of R750 to battery. When energized over this circuit, the relay R150 first completes, at the "X" contacts associated with RA751, an obvious holding circuit for itself. At RA751, the relay R750 also completes a holding circuit for the relay R630, this circuit extending by way of the grounded conductor C336, RA751, RA643, RA727, RA626 and the winding of R630 to battery. At its armatures RA752 to RA756, inclusive, the relay R750 thereafter connects the conductors C326, C327, C328, C329 and C338 through to the relay sets 761 to 765, inclusive, so that the relays embodied in these sets are controlled in accordance with ground pulses impressed upon the enumerated conductors through operation of the interrupter switch 370. At RA751, the relay R750, upon fully operating, interrupts a point in the common portion of its own operating circuit and the operating circuit for the relay R630. When a ground pulse is applied to the conductor C326 by the interrupter switch 370 following operation of the relay R750, a circuit is completed for energizing the relay R640. This circuit extends by way of the grounded conductor C326, RA752, RA723 and the winding of R640 to battery. Upon operating, the relay R640 opens, at RA643, the above-traced holding circuit for the relay R630, thereby to initiate the sequential restoration of the relays R630 and R640. At RA641, the relay R640 completes the above-mentioned circuit for energizing the master relay R600, this circuit extending from ground by way of RA641, RA627 and the winding of R600 to battery. The relay R600 now operates to complete at its armatures RA601, RA602, etc., paths including the left winding of R603 for impressing ground potential upon the associated terminals 766, 767, etc.; these terminals being connected to the terminals of the line relays embodied in the apparatus of Fig. 2 in the manner more fully explained subsequently. The relay R600 is maintained in its operated position for only a predetermined portion of the time interval during which R640 is operated. Thus, shortly following the operation of R640, the relays R630 and R625 sequentially restore to open at RA627 the operating circuit for R600 causing the last-named relay to restore to disconnect ground from the associated terminals 766, 767, etc. At RA642, the relay R640, upon operating, prepares a path for impressing ground potential upon the ringing control conductor C645; this path being completed upon the subsequent release of the relay R625 and extending from ground by way of RA628 and RA642 to the conductor C645. This path is not interrupted until the relay R640 restores subsequent to the release of the relay R625. From the foregoing explanation it will be apparent that during one portion of the interval when the relay R640 is operated, namely, the first ringing interval of the first cycle of operation of the interrupter switch 370, the relay R600 is operated. During the second period of the interval when the relay R640 is operated, the relay R600 is restored and ground potential is impressed upon the ringing control conductor C645. The relative lengths of these two periods is obviously determined by the slow-to-release characteristics of the two relays R630 and R625. Preferably, 75

these relays are so constructed and arranged that the relay R600 is operated for the first quarter of each interval during which the relay R640 is energized, while ground potential is impressed upon the ringing control conductor C645 for the remaining three-quarters of each interval when the relay R640 is energized.

The relay R640, upon operating in the manner explained in the preceding paragraph, also completes a circuit for energizing the relay R655 of the second relay set 762; this circuit extending by way of the grounded start conductor C336, RA757, RA643 and the winding of R655 to battery. At RA644, the relay R640 opens a point in the circuit, traced hereinafter, for energizing the relay R660 at the beginning of the second ringing interval of each ringing cycle. The relay R655, upon operating, completes, at RA656, an obvious circuit for energizing the relay R650. The last-mentioned relay, in turn, operates to prepare a circuit for energizing the second master relay R605 and to open at RA652 a point in the path, traced hereinafter, for impressing ground potential upon the second ringing control conductor C646. At the end of the first ringing interval, ground potential is removed from the conductor C326 and is impressed upon the conductor C327 in the manner previously explained. When this occurs the relay R640 is deenergized and restores to open, at RA641, a further point in the operating circuit for the first master relay R600 and to interrupt, at RA642, the above-traced path for impressing ground potential upon the ringing control conductor C645. At RA643, the relay R640 interrupts the above-traced operating circuit for the relay R655. At RA644, the relay R640 completes a circuit for energizing the relay R660, this circuit extending by way of the grounded conductor C327, RA753, RA644, and the winding of R660 to battery. Upon operating, the relay R660 completes, at RA661, the above-mentioned circuit for energizing the second master relay R605, this circuit extending from ground by way of RA661, RA651 and the winding of R605 to battery. At RA662, the relay R660 prepares the above-mentioned path for impressing ground potential upon the second ringing control conductor C646. At RA663, the relay R660 completes an obvious circuit for energizing the slow-acting relay R675 of the third relay set 763, thereby to cause the sequential operation of the two relays R675 and R670 in the order named. The relay R670, upon operating, prepares, at RA671, the operating circuit for the third master relay R610 and opens, at RA672, a point in a second path for impressing ground potential upon the ringing conductor C645. At RA674, the relay R660 opens a point in the circuit, traced hereinafter, for energizing the relay R680. The second master relay R605 operates in response to operation of the relay R660 and, at its armatures RA606, RA607, etc., completes obvious paths for impressing ground potential upon the associated terminals 768, 769, etc. A predetermined time interval following operation of the relay R605 and when the relays R655 and R650 sequentially restore, to open, at RA651, the operating circuit for R605, this relay restores, to open the above-mentioned ground paths extending to the terminals 768, 769, etc. A path including RA652 and RA662 is also completed for applying ground potential to the ringing control conductor C646 when the relays R650 and R655 restore.

At the end of the second ringing interval of the

ringing cycle under consideration, ground potential is removed from the conductor C327 and is impressed upon the conductor C328 to initiate the third interval of the ringing cycle. When ground potential is removed from the conductor C327, the relay R660 is deenergized and restores to open, at RA662, the above-traced path for impressing ground potential upon the ringing conductor C646; to interrupt, at RA663, the operating circuit for the relay R675, thereby to initiate the sequential restoration of the relays R675 and R670; and to complete, at RA664, a circuit for energizing the relay R680. The last-mentioned circuit extends by way of the grounded conductor C328, RA754, RA664 and the winding of R680 to 15 battery. Upon operating, the relay R680 completes, at RA681, a circuit extending by way of RA671 for energizing the third master relay R610. At RA682, the relay R680 prepares a point in the second path for impressing ground potential upon the ringing control conductor C645. At RA683, the relay R680 completes a circuit for energizing the relay R695 of the fourth relay set 764; this circuit extending by way of the grounded conductor C328, RA754, RA664, RA683 and the winding 25 of R695 to battery. When this circuit is completed, the two relays R695 and R690 sequentially operate in the order named and in an obvious manner. At RA684, the relay R680 opens a point in the operating circuit, traced hereinafter, for 30 the relay R700. The third master relay R610, upon operating its armatures RA611, RA612, etc., connects ground potential to the associated terminals 770, 771, etc. A predetermined time interval following operation of the relay R610 and 35 when the relays R675 and R670 sequentially restore, the operating circuit for R610 is interrupted at RA671, and the second path for impressing ground potential upon the conductor C645 is completed; this path extending from ground by way 40 of RA672 and RA682 to the conductor C645.

At the end of the third interval of the ringing cycle under consideration, ground potential is removed from the conductor C328 by the interrupter switch 370 and is impressed upon the conductor C329 to initiate the fourth ringing interval of the cycle. When ground potential is removed from the conductor C328, the relay R680 is deenergized and restores to open, at RA681, a further point in the operating circuit for the 45 third master relay R610; to open, at RA682, a point in the second path for impressing ground potential upon the ringing control conductor C645; and to open, at RA683, the above-traced operating circuit for the relay R695, thereby to 50 initiate the sequential restoration of the relays R695 and R690. At RA684, the relay R680, upon restoring, completes a circuit for energizing the relay R700, this circuit extending by way of the grounded conductor C329, RA755, RA684 and the 55 winding of R700 to battery. Upon operating, the relay R700 completes, at RA701, a circuit extending by way of RA691 for energizing the fourth master relay R615, which latter relay, upon operating its armatures RA616, RA617, etc., impresses 60 ground potential upon the associated terminals 772, 773, etc., over obvious paths. At RA702, the relay R700 prepares a point in a second path for impressing ground potential upon the second ringing control conductor C646. At RA704, the 70 relay R700 opens a point in the operating circuit, traced hereinafter, for the relay R720 of the fifth relay set 765. At RA703, the relay R700 completes a circuit for energizing the relay R715, this circuit extending by way of the grounded conduct- 75

tor C329, RA755, RA684, RA703 and the winding of R715 to battery. When energized over the circuit just traced, the relay R715 and its associated slow-acting relay R710 operate in the order 5 named, the last-mentioned thereof functioning to prepare an operating circuit for the fifth master relay R620 and to open, at RA712, a point in a third path for impressing ground potential upon the ringing control conductor C645. A predetermined time interval following operation of the 10 fourth master relay R615 and when the relays R695 and R690 sequentially restore, the operating circuit for R615 is interrupted. The relay R615 now restores to disconnect the associated terminals 15 712, 713, etc., from ground. At RA692, the relay R690 completes the second path, including the operated armature RA702, for impressing ground potential upon the second ringing control conductor C646. 20 At the end of the fourth interval of the ringing cycle under consideration, the interrupter switch 370 operates in the manner previously explained to remove ground potential from the conductor C329 and to impress ground potential upon the conductor C338. When the conductor C329 is disconnected from ground, the relay R700 is deenergized and restores to open, at RA701, a further point in the operating circuit for the 25 fourth master relay R615, and to open, at RA702, a point in the second path over which ground potential is impressed upon the ringing control conductor C646. At RA704, the relay R700 completes a circuit for energizing the relay R720, this circuit extending by way of the grounded 30 conductor C338, RA756, RA704 and the winding of R720 to battery. At RA703, the relay R700 interrupts the previously traced operating circuit for the relay R715, thereby to initiate the sequential restoration of the last-named relay and the 35 relay R710. The relay R720, upon operating, opens, at RA723, a point in the previously traced operating circuit for the relay R640 and opens, at RA721, a point in the previously traced operating circuit for the relay R750. At RA721, the 40 relay R720 completes the above-mentioned circuit for energizing the fifth master relay R620, this circuit extending from ground by way of RA721, RA711 and the winding of R620 to battery. When this circuit is completed, the relay 45 R620 operates its associated armatures RA621, RA622, etc., to connect the associated terminals 714, 715, etc., to ground over an obvious path. At RA722, the relay R720 prepares the third path for impressing ground potential upon the ringing 50 control conductor C645, this path being completed at RA712 in response to the subsequent release of the relay R710 simultaneously with the deenergization of the fifth master relay R620. This fifth master relay, upon restoring, opens, at 55 60 its armatures RA621, RA622, etc., the paths over which ground potential is impressed upon the terminals 714, 715, etc. At RA722', the relay R720, upon operating, completes an alternative circuit for energizing the relay R630 of the first 65 relay set 761, this alternative circuit extending by way of the grounded conductor C338, RA756, RA704, RA722', RA751 and the winding of R630 to battery. When this alternative circuit is completed, the relays R630 and R625 sequentially operate in the order named and in the manner previously described. At RA724, the relay R720, upon operating, completes a circuit for energizing the slow-to-release relay R730, this circuit extending from ground by way of C336, RA724, 70 75 RA725, RA744 and the winding of R730 to bat-

tery. When energized over this circuit, the relay R730 operates to prepare, at RA731, a holding circuit for itself, and to prepare, at RA732, a circuit for energizing the relay R740. 5 At the end of the fifth interval of the ringing cycle under consideration, the interrupter switch 370 operates in the manner previously explained to remove ground potential from the conductor C338. Substantially simultaneously, ground potential is impressed upon the conductor C326 to 10 initiate the first ringing interval of a second ringing cycle. When the conductor C338 is disconnected from ground in the interrupter switch 370, the relay R720 is deenergized and restores to open, at RA721, a further point in the operating circuit for the fifth master relay R620, and to interrupt, at RA722, the third path for impressing ground potential upon the ringing control conductor C645. At RA722', the relay R720 interrupts the previously traced alternative operating circuit for 15 the relay R630, thereby to initiate the sequential restoration of the last-mentioned relay and the relay R625. At RA723, the relay R720 completes the previously traced circuit for energizing the relay R640. At RA727, the relay R720 20 reprepares the operating circuit for the relay R750. At RA725 and RC726, the relay R720, upon restoring, completes the prepared holding circuit for the relay R730, this holding circuit extending from ground by way of C336, RA731, RC726, 25 RA725, RA744 and the winding of R730 to battery. Following the completion of this holding circuit, the relay R720 opens, at its armatures RA724 and RA725, a point in the previously traced operating circuit for the relay R730. At RA724 30 and its associated resting contact, the relay R720 completes the above-mentioned circuit for energizing the relay R740, this circuit extending from ground by way of C336, RA724, RA732, RA746 and the winding of R740 to battery. The relay R740 35 now operates to reverse the connections of the ringing control conductors C645 and C646 to the associated conductors C747 and C748, this reversal resulting from the operation of the armatures RA741 and RA742. At RA743 and RA744, 40 the relay R740 interrupts the above-traced holding circuit for R730 and completes a holding circuit for itself, the last-mentioned holding circuit extending from ground by way of C336, RA731, RC726, RA725, RA744, RA743 and the winding of R740 to battery. Substantially simultaneously 45 with the interruption of the initially completed holding circuit for the relay R730, an alternative holding circuit is completed for this relay, this alternative holding circuit extending from ground by way of C336, RA724, RA732, RA746, RA745 and the winding of R730 to battery. Thus, the two relays R730 and R745 are maintained in their respective operated positions during the second 50 cycle of operation of the interrupter switch 370. 55 Following the second operation of the relay R640 in the manner pointed out in the preceding paragraph, the relay sets 761 to 765, inclusive, and their respective associated master relays sequentially operate during the second ringing 60 cycle in the exact manner just described. More specifically, these relay sets operate in a cyclic manner, each cycle of operation thereof corresponding to one cycle of operation of the interrupter switch 370. At the end of each even 65 numbered cycle of operation of the indicated relay sets, the reversing relays R730 and R740 are released, these relays remaining in their respective restored positions for the duration of each odd numbered ringing cycle. Thus, at the 70 75

end of the second cycle of operation of the enumerated relay sets and when the relay R720 operates, the previously traced holding circuit for the relay R730 is interrupted at RA724 and 5 its associated resting contact. Substantially simultaneously an alternative holding circuit is completed for the relay R740, this alternative circuit extending from ground by way of C336, RA724, RA725, RA744, RA743 and the winding 10 of R740 to battery. Shortly following the completion of the last-mentioned circuit, the relay R730 restores to open, at RA731, a point in the common portion of the previously traced holding circuits for itself and the relay R740. At RA732, 15 the relay R730 opens a point in another of its holding circuits and a point in the operating circuit for the relay R740. Thereafter, and when the relay R720 restores, the remaining holding circuit for the relay R740 is interrupted at RA724 20 and RA725, causing the relay R740 to restore to reverse the connections of the ringing control conductors C645 and C646 to the two associated ringing control conductors C747 and C748. Following the restoration of the relay R740, this 25 relay and the relay R730 are not again energized until the third cycle of operation of the relay sets 761 to 765, inclusive, is substantially terminated.

The reversing relays R730 and R740 are provided for the purpose of insuring the connection of ground potential alternately to the two ringing control conductors C747 and C748 during alternate ringing intervals covering several ringing cycles. Thus, it will be apparent from the 30 foregoing explanation that the relay sets 761 and 765 both function to impress ground potential upon the ringing control conductor C645 during the intervals when these relay sets are operating. From this it will be apparent that in the absence of the two relays R730 and R740, connected and arranged in the manner just described, ground potential would be impressed upon one of the two conductors C747 and C748 during each of the first, third, and fifth intervals 35 of each ringing cycle, while ground potential would only be impressed on the other of the two enumerated conductors during the second and fourth intervals of each ringing cycle. This would, of course, mean that ground potential 40 would be impressed upon one of the two conductors during adjacent intervals at the beginning and end of each ringing cycle. Such operation is undesirable for reasons which will be apparent from the following description with 45 reference to operation of the reverting call switch illustrated in Fig. 4. When ground potential is removed from the start conductor C336, the operated ones of the relays shown in Fig. 6 are all caused to restore in an obvious manner.

60 Referring now more particularly to the operation of the apparatus illustrated in Fig. 2, to intercept a call routed by way of the connector switch 30 to the line 11, if it be assumed, for example, that the substation C has been disconnected from service or that for some other reason calls intended for this substation are to be intercepted, and further, that the ringing current frequency designating the substation C is the frequency F1 of the generator 301, it will 65 be apparent that in an attempt to signal the substation C the wiper 122 of the frequency selector switch 120 will be operated into engagement with the contact terminating the conductor C306 during the frequency selecting digit dialed at the calling substation. With the wiper 70

122 of the switch 120 occupying this position, each time the ringing relay R320 operates to complete the circuit for projecting ringing current over the called line 11, the relay R220 is energized by this current. The circuit for energizing the relay R220 may be traced as extending from the ungrounded terminal of the generator 301 by way of RA321, C306, the wiper 122, RA113, RA103, the conductor 11b, the condenser 228, the lower winding of R220, the conductor 10 11a, RA101, RA111, the upper winding of R110 and the exchange battery to the grounded terminal of the generator 301. During the first period of each interval when the relay R320 is operated, the master relay R600 is caused to 15 operate in the manner just explained to impress ground potential upon the terminal 766. During each interval when the lower winding of the relay R220 is energized by the alternating ringing current projected over the line 11, this relay 20 vibrates its armature RA227 to engage its associated working contact. Since the relay R600 is energized during the first period of each of these intervals, a circuit is completed for energizing the upper winding of R220 in series with 25 the left winding of the relay R603. This circuit extends from ground by way of the left winding of R603, RA601, the terminal 766, C229, RA227, RA225, the upper winding of R220, RA224, RA242, RA274 and the resistor 279 to battery. 30 Due to the relatively high resistance of the left winding of the relay R603, none of the armatures controlled by the relay R220 is operated when this circuit is completed. Shortly following the completion of the circuit just traced, the slow-to-operate relay R603 operates to complete, at RA604, an obvious path, including its low resistance right winding, which parallels the high resistance left winding of this relay. 35 Accordingly, the current flow through the upper winding of the relay R220 is increased sufficiently to cause this relay to complete its operation. Upon fully operating, the relay R220 completes a holding circuit for itself, which circuit extends from ground by way of RA276, the lower winding of R220, RA226, RA225, the upper winding of R220, RA224, RA223, RA275 and the resistor 279 to battery. Following the completion of this 40 holding circuit, the relay R220 opens, at RA224 and RA225 and their respective associated resting contacts, two points in the previously traced operating circuit for itself. At RA221 and RA222, the relay R220 connects the conductors of the called line 11 to the trunk conductors C283 and C284 extending to the operator's position 200. 45 When its lower winding is energized over the above-traced circuit including the upper winding of R220, the relay R230 first closes the "X" contacts associated with RA232 to complete an obvious holding circuit for itself. Following the 50 completion of this circuit the relay R230 completes its operation to short-circuit, at RA233, its lower winding, thereby to increase the energization of the upper winding of the relay R220. At RA231, the relay R230 opens a point in the 55 circuit, traced hereinafter, for transmitting ring-back tone current through the receiver provided at the calling substation. At RA234, the relay R230 completes an obvious circuit for energizing the upper winding of the slow-to-release relay R240. At RA235, the relay R230 completes a 60 circuit for energizing the signal lamp 204, this circuit extending from ground by way of RA235, RA258 and the filament of the lamp 204 to battery. At RA235, the relay R230 also prepares 65

a path, traced hereinafter, for short-circuiting the upper winding of the relay R540. The relay R240, upon operating, prepares, at RA244, a holding circuit for the relay R270, and opens, at 5 RA243, one of the multiple holding circuits for the relay R230. At RA242, the relay R240 opens a point in the common portion of the operating circuits for the line relays corresponding to and including the relay R220 and individually associated with the multiparty lines arranged for 10 call interception. At RA241, the relay R240 prepares the above-mentioned circuit for transmitting ring-back tone current through the receiver provided at the calling substation. Following operation of the relay R240 no further 15 operation of the apparatus occurs until the call is answered at the operator's position 200.

To answer the call, the operator attending the position 200 operates the key 201 to its off-normal 20 position to prepare, at the springs 206 and 207, a talking circuit extending between the telephone set 202 and the calling subscriber's substation. At the contact springs 208, an obvious circuit is completed for energizing the lower winding of 25 the relay R250. The relay R250, upon operating, completes, at RA256, a multiple holding circuit for the operated line relay R220. At RA257, the relay R250 completes an obvious circuit for energizing the slow-to-operate relay R260. At 30 RA258, the relay R250 opens a point in the above-mentioned path for energizing the signal lamp 204. At RA254, the relay R250 interrupts the previously traced holding circuit for the relay R230, causing the last-named relay to restore. 35 At RA253, the relay R250 completes a circuit for energizing the ring cutoff relay R110 embodied in the connector switch 30, this circuit extending from ground by way of the resistor 282, the left winding of the impedance element 280, RA253, C284, RA222, the conductor 11a, RA101, RA111 and the upper winding of the relay R110 to battery. The resulting operation of the relay R110 causes the ringing operation to be terminated and a loop circuit extending from the connector 40 switch 30 to the trunk line conductors C283 and C284 to be completed. At RA251, the relay R250, upon operating, opens a point in the circuit, traced hereinafter, for energizing the relay R530.

Shortly following operation of the relay R250, 45 the slow-to-operate relay R260 operates to complete, at RA263, an obvious holding circuit for the slow-to-release relay R240. At RA261, the relay R260 completes an obvious multiple holding circuit for the operated line relay R220. At 50 RA262, the relay R260 completes an obvious circuit for energizing the relay R270. The relay R230, upon restoring in response to operation of the relay R250, opens, at RA231, a point in the above-mentioned path for transmitting ring-back tone current to the calling substation, and 55 opens, at RA232, a further point in its own holding circuit. At RA234, the relay R230 interrupts the operating circuit for the relay R240. At RA235, the relay R230 interrupts the circuit for 60 energizing the signal lamp 204 and opens a point in the previously mentioned path for short-circuiting the upper winding of the relay R540. When the relay R270 operates it prepares, at RA271, a point in the circuit, traced hereinafter, 65 for energizing the relay R530 and interrupts, at RA274 and RA275, the operating circuit and the initially completed holding circuit for the operated line relay R220. At RA276, the relay R270 opens a point in the previously traced circuit for 70 energizing the lower winding of R230 in series

with the upper winding of the relay R220. At RA277, the relay R270 completes a holding circuit for itself, this holding circuit extending from ground at RA244 by way of RA271 and the winding of R270 to battery. At RA278, the relay R270 5 opens a further point in the above-mentioned path for short-circuiting the upper winding of the relay R540. Finally, at its armatures RA272 and RA273, the relay R270 completes the desired talking circuit between the operator's telephone set 202 and the calling substation. 10

If, following the completion of the desired talking circuit in the manner just explained, the operator attending the position 200 desires to free her telephone set for use in answering another call without releasing the established connection extending to the calling substation A, she may do so by first operating the key 203 to its off-normal position and then restoring the answer key 201 to its normal position. When the 20 key 203 is actuated to its off-normal position, an obvious multiple holding circuit is completed at the springs 209 for the operated relay R250. At the springs 210, an obvious circuit is completed for energizing the signal lamp 205. Following 25 the completion of the holding circuit for the relay R250, the answer key 201 may be restored to normal to open the operating circuit for the relay R250 without initiating the release of the relays of the apparatus shown in Fig. 2. Operation of the key 201 to its normal position also disconnects the telephone set 202 from the established talking circuit extending to the calling substation A so that this telephone set may be used in handling other calls routed to the operator's position 200 over other trunk circuits. In order to reconnect her telephone set to the established talking circuit and to recomplete, at the springs 208, the operating circuit for the relay R250. Following operation of the key 201 to its off-normal position, the key 203 may be restored to normal without releasing the established connection. When the key 203 is restored to normal, the springs 210 embodied therein are disengaged 30 to open the circuit for energizing the signal lamp 205. 35

The release of the apparatus illustrated in Fig. 2 is entirely under the control of the operator attending the position 200. Thus, if the calling subscriber hangs up before the operator clears out the connection, the operated switch train including the line switch 20, the selector switch 25, and the connector switch 30, is released in the exact manner previously described. During the release of the connector switch 30, the loop circuit extending from this switch to the operator's position 200 is interrupted and negative battery potential is substituted for ground potential upon the control conductor of the called line 11, thereby to mark this line as idle in the bank contacts of the connector switches having access thereto. Interruption of the loop circuit extending from the connector switch 30 to the apparatus shown in Fig. 2 in no way influences the operated relays embodied in this apparatus. When, however, the 40 operator restores the answer key 201 to normal, the springs 208 are opened to interrupt the operating circuit for the relay R250. This relay, upon restoring, opens, at RA257, the operating circuit for the relay R260, which latter relay, in turn, 45 50 55 60 65 70 75

restores to open, at RA283, the holding circuit for the relay R240. Upon restoring, the relay R250 also interrupts, at RA288, the circuit over which the upper winding of the line relay R220 is being held energized, thus causing the last-named relay to release. When the relay R240 restores, it opens, at RA244, the holding circuit for the relay R270, causing the last-mentioned relay to restore. Thus, all of the relays embodied in the apparatus shown in Fig. 2 are restored to normal and this apparatus is conditioned for use in routing another call to the operator's position 200.

From the foregoing explanation, it will be apparent that the call intended for the substation C associated with the line 11 was intercepted and routed to the operator's position 200 through operation of the apparatus shown in Fig. 2 only because the intervals during which the relay R220 was energized by ringing current projected over the line 11 partially overlapped the periods during which the relay R600 was operated. With the circuit connections illustrated, only calls routed to the line 11 and intended for the substation C will be intercepted and extended to the operator's position 200. This is by virtue of the arrangement whereby the ringing intervals during which ringing currents of the frequencies corresponding to the other substations associated with the line 11 are transmitted to the connector switches having access to this line do not overlap the periods when the master relay R600 is operated. Thus, on a call intended for the substation B, ringing current is only projected over the line 11 to energize the relay R220 during the intervals overlapping the periods when the fourth master relay R615 is operated. Accordingly, the partial operation of the relay R220 effected through energization of this relay by the ringing current is ineffective to initiate the operation of the trunk circuit apparatus. It will be apparent, however, that by properly connecting the conductor C229 to the terminals controlled by the other master relays R605, R610, R615 and R620, calls to any of the substations associated with the line 11 may be intercepted and routed to the operator's position 200. For example, if the conductor C229 is disconnected from the terminal 766 and connected to the terminal 772, the operating circuit for the relay R220 will be completed during those intervals when ringing current for signaling the substation B is projected over the line 11. As a further example, if the conductor C229 is connected to both of the terminals 766 and 772 the operating circuit for the relay R220 will be completed each time ringing current of the frequencies respectively corresponding to the substations B and C is projected over the line 11. Thus, by appropriately connecting the conductor C229 to the terminals respectively associated with the five master relays, calls to any desired one or ones of the substations associated with the line 11 may be intercepted and routed to the operator's position 200.

It will also be apparent from the foregoing explanation that the use of the trunk circuit apparatus shown in Fig. 2 is not limited to the interception of calls routed to a single multiparty subscriber's line embodied in the system. On the contrary, this apparatus may be connected to serve any number of multiparty subscribers' lines through the provision of additional line relays corresponding to the relay R220 and provided in individual association with the lines with respect to which call interception is desired. In this regard, it will be understood that the windings of

these additional line relays corresponding to the lower winding of R200 will be respectively bridged across the conductors of their respective associated line. In addition, the bracketed conductors C236 will be multiplied to the contacts of the additional line relays respectively corresponding to the contacts of the relay R220 to which these conductors individually extend. Further, the armatures of the other line relays, respectively corresponding to RA227 of the relay R220, will be connected to those of the terminals 766 to 775, inclusive, which correspond to the substations with respect to which calls are to be intercepted. With a second of the additional line relays connected in the manner just explained, if a call to be intercepted is routed by way of the line associated with this second relay the apparatus shown in Fig. 2 will respond to the operation of the second relay in the manner set forth above. During the operation of this apparatus and when the relay R240 operates, this relay opens, at RA242, a point in the common portion of the operating circuits for all of the line relays, thus preventing subsequently initiated calls which would normally be intercepted from being routed through the apparatus of Fig. 2 to the operator's position 200 until this apparatus is released. With the arrangement illustrated, no provisions are made for discriminating between two calls which would normally be intercepted and which are simultaneously initiated. In such case the line relays individually associated with the two lines to which the calls are routed will both operate so that both of the calls will be routed to the operator's position 200. This type of operation is, however, not objectionable since the operator attending the position 200 is easily capable of handling the two calls without confusion.

If all calls to one or more of the lines of the system are to be intercepted, the relay R290 may be connected and arranged to be used in lieu of the apparatus shown in Fig. 6 in controlling the line relays associated with such lines. Thus, if all calls to the line 11 are to be intercepted, the conductor C229 may be disconnected from the control terminals of the apparatus shown in Fig. 6 and connected through the lower winding of the slow-to-operate relay R290 and the lower winding of R230 to ground at RA276 in the manner indicated by the dotted line conductors. As thus connected, if ringing current is projected over the line 11 to energize the lower winding of the relay R220 the resulting vibration of RA227 causes a circuit to be completed for energizing the upper winding of R220, this circuit extending from ground by way of RA276, the lower winding of R230, the lower winding of R290, RA227, RA225, the upper winding of R220, RA224, RA242, RA274 and the resistor 279 to battery. Due to the relatively high resistance of the lower winding of R290, the relay R220 does not operate when energized over this circuit. The relay R290, however, operates after an interval to complete, at RA291, an obvious path, including its low resistance upper winding, in multiple with its lower winding. When this path is completed the relay R220 completes its operation to cause the call to be extended to the operator's position 200 in the manner previously explained. Upon fully operating, the relay completes the previously traced holding circuit for itself which circuit does not include the windings of R290. Accordingly, the relay R290 restores shortly following the complete operation of the line relay R220.

As previously pointed out, the slow-to-operate

relays R290 and R603 are provided for the purpose of preventing false call interception on lines arranged for call interception, due to transient surges impressed upon such lines. For example, if a lightning surge should occur on the line 11 the lower winding of the relay R220 would be energized thereby. If the surge should occur with ground potential directly impressed upon the conductor C229, the relay R220 would immediately complete its operation to cause a call falsely to be forwarded to the operator's position 200. With the arrangement illustrated, however, the slow-to-operate characteristics of the relays R290 and R603 delay the full energization of the upper 15 winding of the line relay R220 for a period substantially exceeding the duration of transients of the character mentioned. Accordingly, the relay R220 is prevented from falsely operating when energized by voltages of unsustained transient 20 character.

Although the apparatus illustrated in Fig. 2 has been described with reference to the interception of calls arranged for bridged ringing, it will be understood that the circuits are also 25 adapted for use in association with multiparty subscribers' lines arranged for divided ringing. In the latter case the alternating current windings of the line relays, such, for example, as the relay R220, individually associated with the lines 30 arranged for call interception, may be arranged to be bridged between both sides of their respective associated lines and ground through the provision of impedance bridge arrangements. As thus connected, each of the line relays would be 35 energized by ringing current projected over either side of its associated line. In the line connecting apparatus shown in Fig. 2, provisions are made for operating the ring cutoff relay of an operated connector switch arranged for divided ringing. 40 Thus, in the operation of the apparatus described above, the ring cutoff relay R110 of the connector switch was energized in response to operation of the relay R250 over a circuit including the resistor 282 and the left winding of the impedance element 280. A similar circuit would be completed if the connector switch were arranged for 45 divided ringing and ringing current was projected therefrom over the side of a selected called line arranged for connection to the line conductor 50 C283, this similar circuit including the resistor 281 and the right winding of the impedance element 280. Thus, it will be apparent that the arrangement illustrated in Fig. 2 is adapted, without modification, for use in conjunction with automatic switching apparatus arranged to serve 55 lines requiring divided ringing, bridged ringing, or both types of ringing.

With the arrangement illustrated, no provision is made for intercepting a call initiated at 60 one station on a multiparty line and intended for another station on the same line with respect to which calls are normally intercepted. More particularly, if a call initiated at the substation B and intended for the substation D is routed by way of the line switch 15 to the selector switch 65 25 in the manner previously explained with reference to the call initiated at the substation A, the substation D is signaled by dialing the three digits of the reverting call directory number designating this substation. The selector switch 25 responds to the impulses of the first digit by elevating its wipers to a position opposite the level of bank contacts terminating the trunk lines extending to the reverting call switches. 70 At the end of the digit and during the interdigit

pause between the first and second digits, the wipers of the selector switch 25 are automatically rotated over the contacts of the selected level to select an idle one of the reverting call switches. Assuming, for example, that the reverting call 5 switch illustrated in Fig. 4 is the first idle switch available, when the wipers of the selector switch 25 encounter the contacts terminating the conductors of the trunk line 33 extending to this reverting call switch, the calling loop circuit is 10 extended to the last-mentioned switch and the line relay R430 is energized thereover. This relay, upon operating, completes, at RA431, an obvious circuit for energizing the slow-acting hold relay R435. Upon operating, the relay R435 15 opens, at RA436, a point in the path, traced hereinafter, for impressing negative battery potential upon the control conductor 34 of the trunk line 33. At RA436 and its associated working contact, the relay R435 completes a path including the 20 restored armature RA461 for impressing ground potential upon the control conductor 34, thereby to mark the trunk line 33 as busy in the bank contacts of the selector switches having access thereto and to complete a circuit for maintaining 25 certain of the relays embodied in the selector switch 25 operated. Thus the switches 20 and 25 are prevented from releasing. At RA437, the relay R435 prepares a circuit for energizing the slow-to-release relay R445 in parallel with the 30 rotary magnet 415 of the minor switch 410 during the impulses of the second digit. At RA438, the relay R435 opens a point in the common portion of the circuits, traced hereinafter, for energizing the release magnets 406 and 416 of the 35 frequency selecting switches 400 and 410 respectively. Each time the line relay R430 restores in response to an impulse of the second digit dialed at the calling substation it functions to open, at RA431, the operating circuit for the hold relay R435, and to complete the above-mentioned 40 circuit for energizing the relay R445 in parallel with the rotary magnet 415. This latter circuit extends from ground by way of RA431, RA437 to RA442 where it divides, one branch extending 45 through the winding of R445 to battery and the other branch extending by way of RA453 and the winding of the magnet 415 to battery. The relay R445, upon operating, opens, at RA446, a point in the circuit for energizing the relay R450, and, at RA447, a point in the circuit for energizing 50 the relay R440. The relays R435 and R445, due to their slow-to-release characteristics, remain operated during impulsion.

Each time the rotary magnet 415 is energized 55 it functions to advance the wipers 413 and 414 one step so that at the conclusion of the second digit dialed at the calling substation these wipers are left standing in a position corresponding to the frequency of the ringing current required to cause the operation of the tuned ringer 14 provided at the called substation D. The two frequency selecting switches 400 and 410 are arranged to select the side of a subscriber's line over which ringing current is to be projected 60 when used in conjunction with the multiparty subscribers' lines of the system which are arranged for divided ringing. These switches will, however, operate equally satisfactorily in ringing over the lines, such, for example, as the line 70 11, arranged for bridged ringing. In the present case, if it be assumed, for example, that the ringer 14 provided at the called substation D is tuned to respond to ringing current of the frequency F3 developed by the generator 303, the 75

second digit dialed at the calling substation B may comprise either three or eight impulses. Assuming that a second digit of three impulses is dialed at the calling substation, the wipers 413 and 414 are left standing in engagement with their respective associated third contacts at the end of the second digit. When these wipers are stepped to their respective first off-normal positions, the off-normal springs 417 are moved into engagement to prepare a circuit for energizing the digit transfer relay R450. This circuit is completed shortly following the end of the second digit when the relay R445 restores. Specifically, this circuit extends from ground by way of the off-normal springs 417, RA446 and the winding of R450 to battery. Upon operating, the relay R450 opens, at RA451, a further point in the above-mentioned path for impressing negative battery potential on the control conductor 34 of the trunk line 33, and completes, at RA452, a holding circuit for itself, this holding circuit extending from ground by way of the off-normal springs 417, RA452 and the winding of R450 to battery. At RA453 and its associated resting contact, the relay R450 opens a point in the above-traced circuit for energizing the operating magnet 418 of the minor switch 410. At RA453 and its associated working contact, the relay R450 prepares a circuit for energizing the operating magnet 405 in accordance with the impulses of the third digit of the reverting call directory number designating the called substation D. At RA454, the relay R450 prepares the previously mentioned circuit for energizing the release magnet 416.

Each time the line relay R430 restores in response to an impulse of the third digit dialed at the calling substation, the above-mentioned circuit is completed for energizing the slow-acting relay R445 in parallel with the operating magnet 405 of the minor switch 400. The branch of this circuit which extends through the winding of the magnet 405 may be traced as extending from ground by way of RA431, RA431, RA442, RA453 and the winding of the magnet 405 to battery. Each time this magnet is energized it operates to advance the wipers 403 and 404 one step. At the end of the third digit, therefore, these wipers are left standing in engagement with the contacts corresponding to the frequency of the ringing current to which the ringer 12, provided at the calling substation B, is tuned to respond. When the indicated wipers are stepped to their respective first off-normal positions, the off-normal springs 407 are closed to prepare a circuit, traced hereinafter, for energizing the relay R440. In the present assumed case wherein the ringer 12 provided at the calling substation B is tuned to respond to ringing current of the frequency F2 developed by the generator 302, the third digit dialed at the calling substation may comprise either two or seven impulses such that one of the two wipers 403 and 404 will, at the end of the digit, engage a contact connected to the conductor 371 extending to the ungrounded terminal of the generator 302. Assuming a third digit of two impulses is dialed at the calling substation, the wipers 403 and 404 are advanced, during the impulses of this digit, into engagement with their respective associated second contacts where they remain until the reverting call switch is released. Shortly following the end of the third digit, the relay R445 restores to complete, at RA447, the above-mentioned circuit for energizing the relay R440, this

circuit extending from ground by way of the off-normal springs 407, RA447 and the winding of R440 to battery. Upon operating, the relay R440 opens, at RA442 and its associated resting contact, a point in each of the above-traced pulsing circuits extending through the respective windings of the magnets 405 and 418. At RA442 and its associated working contact, the relay R440 prepares a circuit, traced hereinafter, for energizing the line switching relay R420. At RA441, the relay R440 opens a further point in the path for impressing negative battery potential upon the control conductor 34 of the trunk line 33. At RA443, the relay R440 prepares the above-mentioned circuit for energizing the release magnet 400.

After dialing the third digit in the manner just explained, the calling subscriber replaces the receiver of his telephone instrument upon its supporting hook or cradle, so that the loop circuit extending through the switches 15 and 25 and over the trunk line 33 to the reverting call switch is interrupted. As a result, the line relay R430 is deenergized and restores to complete the above-mentioned circuit for energizing the line switching relay R420. At RA431 and its associated working contact, the relay R430 opens the operating circuit for the slow-to-release hold relay R435. The circuit for energizing the line switching relay R420 extends from ground by way of RA431, RA431, RA442, RA462 and the winding of R420 to battery. Immediately this circuit is completed, the relay R420 operates to complete, at RA426, an obvious holding circuit for the hold relay R435, thereby to prevent the last-named relay from restoring. At RA421, the relay R420 completes an obvious path for impressing ground potential upon the start conductor C336, thereby to initiate the operation of the interrupter switch 370, the operation of the ringing relays shown in Fig. 3 and the operation of the control apparatus shown in Fig. 6, all in the exact manner previously explained. At RA422 and RA423, the relay R420 connects the ringing control conductors C741 and C748 to the terminals of the two ringing control relays R470 and R465, respectively, thereby to condition these ringing control relays for alternate operation in response to the application of ground potential alternatively to the two indicated ringing control conductors. At RA424 and RA425, the relay R420 disconnects the line terminals of the line relay R430 from the line conductors of the trunk line 33 and connects the indicated trunk line conductors to conduct ringing current to the line 11.

Following the operation of the relay R420, ringing currents of the frequencies F2 and F3 are alternately projected over the line 11, thereby alternately to energize the tuned ringers 14 and 12 provided at the called and calling substations, respectively. Thus, when ground potential is impressed upon the ringing control conductor C645 during the second period of the first interval of the first ringing cycle which occurs following operation of the relay R420, a circuit is completed for energizing the ringing control relay R470, this circuit extending by way of the grounded conductor C645, RA741, C741, RA422 and the winding of R470 to battery. When energized over this circuit, the relay R470 operates to complete at RA471, RA472, and RA473 the above-mentioned circuit for transmitting ringing current of the frequency F3, 75

designating the called substation D, over the line 11. The circuit traversed by this current extends from the ungrounded terminal of the generator 303 by way of the conductor C312, the 5 third contact of the set 412, the wiper 414, RA412, the winding of the relay R455, RA425, one side of the connection extending to the substation D, the windings of the ringer 14 bridged across the line 11 in series with the condenser 18, the other side of the connection extending from the substation D to the reverting call switch, RA424, the resistor 457, RA471, the wiper 413, the third contact of the set 411, RA473 and the exchange battery to the grounded terminal 10 of the generator 303. Portions of the ringing current are by-passed through the bridged ringers provided at the other substation associated with the line 11, but since the ringer 14 is the only one of the ringers tuned to the frequency F3 of the generator 303 this ringer is the only one which operates.

At the end of the second period of the first interval of the first ringing cycle and when the relay R460 restores in the manner pointed out 15 previously to disconnect ground from the conductor C645, the relay R470 restores to open the above-traced circuit over which ringing current of the frequency F3 is conducted to the ringer 14 provided at the called substation D. 20 During the second period of the second interval of the first ringing cycle when ground potential is impressed upon the ringing control conductor C646 in the manner previously explained, the relay R465 is energized over a circuit extending 25 by way of the grounded conductor C646, RA742, C748, RA423 and the winding of R465 to battery. When energized over this circuit, the relay R465 operates to complete a circuit for transmitting ringing current of the frequency F2, designating 30 the calling substation B, over the line 11. The path traversed by this current may partially be traced as extending from the ungrounded terminal of the generator 302 by way of C311, the second contact of the set 401, the wiper 403, RA466, 35 the resistor 451, RA424, one side of the connection extending to the line 11, the bridged ringer 12 and condenser 16 provided at the calling substation B, the other side of the connection extending between the line 11 and the reverting 40 call switch, RA425, the winding of R455, RA467, the wiper 404, the second contact of the set 402, RA468 and the exchange battery to the grounded terminal of the generator 302. Only the tuned ringer 12 provided at the calling substation B responds to this ringing current, since the other ringers associated with the line 11 are tuned to respond to ringing currents over other frequencies. At the end of the second period 45 of the second ringing interval when ground potential is removed from the conductor C646, the relay R465 is deenergized and restores to interrupt the circuit just traced for conducting ringing current of the frequency F2 through the ringer provided at the calling substation B.

60 From the foregoing explanation with reference to the apparatus illustrated in Fig. 6, it will be recalled that ground potential is alternately impressed upon the ringing control conductors C747 and C748 during the respective second 65 periods of the alternate ringing intervals. Accordingly, it will be apparent that the two relays R470 and R465 alternately operate to cause the alternate operation of the ringers 14 and 12 provided at the called and calling substations 70 D and B, respectively. Such alternate operation 75

of the two ringing control relays continues until the call is answered at the called substation or the call is abandoned by the calling subscriber. In this regard, it is pointed out that to abandon the call the calling subscriber momentarily removes his receiver from its hook to complete for a short time interval a direct current loop circuit between the calling substation and the reverting call switch. In either case, a direct current bridge is connected between the conductors of the line 11 to complete a circuit for energizing the slow-acting ring cutoff relay R455. This circuit is substantially similar to those traversed by the ringing currents transmitted over the line 11 to the calling and called substations. Upon operating, the relay R455 completes, at RA456, an obvious circuit for energizing the relay R460. The relay R460, upon operating, opens at RA461 and its associated resting contact a point in the above-traced circuit 10 for impressing ground potential upon the control conductor 34 of the line 33, thereby to initiate the release of the selector switch 25 and the line switch 15 in the usual manner. At RA461 and its associated working contact, the relay R460 15 completes a holding circuit for itself, this holding circuit extending from ground by way of RA436, RA461 and the winding of R460 to battery. Shortly following the operation of the relay R460 and during the release of the selector 20 switch 25, the loop circuit extending from the line 11 to the reverting call switches is interrupted causing the ring cutoff relay R455 to restore and open the operating circuit for the relay R460. Upon operating, the relay R460 25 also opens, at RA462, the previously traced circuit for energizing the relay R420 causing the last-named relay to restore. Upon restoring, the relay R420 opens, at RA421, the path for impressing ground potential upon the start conductor C336. At RA422 and RA423, the relay R420 disconnects the ringing control leads C747 and C748 from the terminals of the ringing control relays R470 and R465, thereby to discontinue the alternate operation of these two 30 relays. At RA426, the relay R420 opens the holding circuit for the relay R435. Shortly thereafter and when the last-named relay restores, the above-mentioned circuits are completed for energizing the release magnets 406 and 416. One 35 of these circuits extends from ground by way of RA438, RA443 and the winding of the magnet 406 to battery, while the other circuit extends from ground by way of RA438, RA454 and the winding of the magnet 416 to battery. The relay R435, 40 upon restoring, also interrupts at RA436 the above-traced holding circuit for the relay R460 causing the last-named relay to restore. When the magnet 406 is energized, the wipers 403 and 404 are returned to their respective home 45 positions in the usual manner, at which time the off-normal springs 407 are opened to interrupt the above-traced operating circuit for the relay R440. Similarly, when the magnet 416 is energized, the wipers 413 and 414 are returned 50 to their respective home positions and the off-normal springs 417 are disengaged to open the holding circuit for the relay R450. When the two relays R440 and R450 restore, the previously 55 mentioned path for impressing negative battery potential upon the control conductor 34 of the line 33 is completed, this path extending from the negative terminal of the exchange battery by way of the resistor 448, RA451, RA441, RA436 and RA461 to the conductor 34. Following the res- 60

70

75

toration of the two relays R448 and R450, the reverting call switch illustrated in Fig. 4 is fully released and is rendered available for further use. From the preceding description with reference 5 to the reverting call connection completed between the substations B and D, it will be apparent that in no instance is either of the two ringing control relays R465 and R470 operated to project ringing current over the line 11 at a 10 time when one of the master relays R600, R605, R610, R615, and R620 is operated. This is by virtue of the arrangement illustrated in Fig. 6 for dividing each ringing interval into two parts, the first part being reserved for operation of one 15 of the master relays and the second part being reserved as a ringing period during which one of the ringing control relays of the reverting call switch may be operated. Accordingly, it will be apparent that call interception is precluded insofar as reverting calls initiated on the multiparty subscribers' lines are concerned. The provision of the arrangement shown in Fig. 6 is necessary in order to prevent the interception of calls intended for substations with respect to 20 25 which no call interception is desired. Thus, with the arrangement illustrated wherein calls intended for the substation C associated with the line 11 are to be intercepted, if either of the two ringing control relays R465 and R470 30 were permitted to operate concurrently with the master relay R600, the trunk circuit apparatus illustrated in Fig. 2 would operate to intercept the call and route the connection to the operator's position 200. In the absence of the 35 apparatus for splitting the ringing intervals in the manner explained previously, the relay R600 and the relay R470 would be concurrently operated to initiate such call interception during the first ringing interval of the odd numbered 40 ringing cycles. Similarly, the master relay R600 and the relay R465 would be concurrently operated to cause interception of the call during the first ringing interval of each of the even numbered ringing cycles. This is true regardless of 45 the identity of the calling and called substations associated with the line 11. By virtue of the ringing interval splitting arrangement, however, such inadvertent call interception on reverting calls is precluded.

50 As indicated in the introductory portion of the specification, the trunk circuit apparatus illustrated in Fig. 2, in cooperation with the apparatus shown in Fig. 5, may be used to extend to the operator's position 200 a connection which 55 has inadvertently been routed to a dead level of bank contacts embodied in one of the selector switches of the system. For example, if the previously described call initiated at the substation A and intended for the substation C is, 60 through improper dialing on the part of the calling subscriber, routed to the level of dead contacts in the selector switch 25, the call is intercepted and a connection is extended to the operator's position 200. More particularly, at the 65 end of the first digit dialed at the calling substation A and when the wipers of the selector switch 25 are started in rotation to search for an idle outgoing trunk line in the selected level, these wipers encounter, upon the first step thereof, the contacts 26, 27 and 28 terminating the 70 trunk line 36. The control apparatus of the selector switch now operates to switch the calling loop circuit through to the equipment illustrated in Fig. 5. The line relay R500 is energized over this loop circuit and operates to com-

plete, at RA501, an obvious circuit for energizing the slow-acting hold relay R510. The hold relay R510, in turn, operates to complete, at RA513, an obvious path for impressing ground potential upon the control conductor 37 of the 5 trunk line 36, thereby to mark the line 36 as busy and to maintain the selector switch 25 and the preceding line switch 20 operated. At RA515, the relay R510 completes a path extending by way of RA536 for impressing ground potential 10 upon the start conductor C336, thereby to initiate the operation of the interrupter switch 370 and of the apparatus illustrated in Fig. 6 in the manner previously explained. At RA511, the relay R510 completes a path including the condenser 15 516, RA531 and RA542 for connecting one of the ringing current conductors such, for example, as the conductor C306 to the trunk line conductor 32, whereby the usual ring-back tone signal is transmitted to the calling subscriber. 20 At RA512 and RA514, the relay R510 completes a circuit for energizing the upper winding of R540 in series with the signal lamp 204, this circuit extending from ground at RA514 by way of the upper winding of R540, RA543, RA512, 25 RA533, C287, RA278, RA258 and the filament of the lamp 204 to battery. When its upper winding is energized over this circuit, the relay R540 partially operates to complete, at the "X" contacts associated with RA544, a holding circuit for itself, this holding circuit extending from ground at RA514 by way of RA534, RA544 and the lower winding of R540 to battery. When this circuit is completed, the relay R540 operates to open, at RA543, a point in the above-traced series circuit 30 including the filament of the lamp 204. At RA542 and its associated resting contact, the relay R540 opens the path for transmitting ring-back tone current to the calling substation. At RA541 and RA542, the relay R540 effectively 40 connects the trunk line conductors 31 and 32 to the line conductors C283 and C284 extending to the operator's position 200. At RA543 and its associated working contact, the relay R540 prepares an alternative circuit for energizing the signal lamp 204. At RA546, the relay R540 prepares a circuit for energizing the relay R530. At RA545, the relay R540 completes a circuit for 45 energizing the lock-out relay R240, this circuit extending from ground by way of RA514, RA534, 50 RA545, C285 and the lower winding of R240 to battery. When energized over this circuit, the relay R240 operates to open, at RA242, a point in the common portion of the operating circuits for the respective line relays individually associated with the multiparty lines arranged for call interception. Thus, the line relays are prevented from operating to extend connections to the operator's position 200 until the call routed through the apparatus shown in Fig. 5 is 55 released. At RA241, the relay R240 completes an alternative path for conducting ring-back tone current to the calling loop circuit. More particularly, when the relay R240 operates, one 60 of the ringing current conductors, such, for example, as the conductor C306, is connected over a path including the condenser 235, RA231, RA241, RA272, C283 and RA541 to one side of the calling line 10. Current transmitted over this 65 path serves to energize the receiver provided at the calling substation, thereby to signal the calling subscriber that a ringing operation is being performed. When the hold relay R510 70 operates in response to operation of the line 75 75

relay R500, it also completes a circuit for energizing the slow-to-operate relay R550, this circuit extending from ground by way of RA514, RA534, the winding of R550 and the resistor 553 to battery. Shortly following its energization over this circuit, the relay R550 operates to complete the above-mentioned alternative circuit for energizing the signal lamp 204, this alternative circuit extending from ground by way of RA514, RA534, RA551, RA543, RA512, RA533, C281, RA278, RA258 and the filament of the lamp 204 to battery. Upon operating, the relay R550 also completes, at RA552, an obvious path for short-circuiting its own winding. Accordingly, the relay 15 R550 restores to open, at RA551, the alternative circuit for energizing the lamp 204. Upon restoring, the relay R550 also opens at RA552 the path short-circuiting its own winding. As a result, this relay reoperates after an interval to 20 recomplete the circuit for energizing the signal lamp 204 and the path for short-circuiting its own winding. Thus, the relay R550 alternately operates and restores intermittently to complete the circuit for energizing the signal lamp 204. 25 The flashing of this lamp serves to signal the operator attending the position 200 that a call intercepted at a dead level of one of the selector switches of the system should be answered. It will thus be apparent that the signal lamp 204 30 operates in one manner, that is, continuously, to signal the operator on a call extended to the operator's position through operation of one of the line relays, such, for example, as the relay R220, and in a different manner, that is, intermittently, on a call routed from an inactive contact set of one of the selector switches through the apparatus illustrated in Fig. 5 to the operator's position. 35

The intermittent operation of the lamp 204 continues until the call is answered by the operator attending the position 200. To answer the call, the operator actuates the key 201 to complete at the springs 208 the previously-traced circuit for energizing the relay R250. This relay, 40 upon operating, initiates the sequential operation of the relays R260 and R270 in the manner previously explained with reference to the call routed by way of the line 11 and intercepted through operation of the line relay R220. At 45 RA251, the relay R250, upon operating, opens a point in the above-mentioned circuit for energizing the relay R530. The relay R270, upon operating, completes, at its armatures RA272 and RA273, the desired talking circuit between 50 the operator's telephone set 202 and the calling substation. At RA271, the relay R270 prepares a point in the circuit for energizing the relay R530. At RA277, the relay R270 completes the previously traced holding circuit for itself. At 55 RA278, the relay R270 opens a further point in the above-traced alternative circuit for intermittently energizing the signal lamp 204.

If the call is not answered at the operator's position 200, the release of the apparatus shown in Figs. 2 and 5 is effected when the call is abandoned at the calling substation. More particularly, if the calling subscriber hangs up to interrupt the calling loop circuit before the operator answers the call, the line and hold 60 relays R500 and R510 sequentially restore in an obvious manner, the last-mentioned thereof opening, at RA514, the holding and operating circuits for the signal lamp 204 and the relays R540, R550 and R240 causing all of these relays 65 to restore to recondition the apparatus of Figs. 2 70 and 5 for further use. Upon restoring, the hold relay R510 also opens, at RA515, the path for impressing ground potential upon the start conductor C336, and disconnects, at RA513, the control conductor 31 of the trunk line 36 from ground. As a result, the selector switch 25 and the preceding line switch 20 are released in the usual manner. When the hold relay R510 restores, it recomplete, at RA513, the previously-mentioned path, extending through the winding 10 of the impedance coil 520, for impressing negative battery potential upon the control conductor 37, thereby to mark the trunk line 36 as idle in the bank contacts of the selector switches having access thereto. 15

Assuming that the call is answered at the operator's position 200 and, further, that the operator clears out the connection before the calling subscriber hangs up, when the key 201 is restored to its normal position, the relays R250 20 and R260 are caused sequentially to restore in an obvious manner. Upon restoring, the relay R250 completes the previously-mentioned circuit for energizing the relay R530, this circuit extending from ground by way of RA502, the 25 lower winding of R530, RA535, RA546, C286, RA271, RA251 and the resistor 259 to battery. When energized over this circuit, the relay R530 first closes the "X" contacts associated with RA537 to complete an obvious holding circuit 30 for itself. Following the completion of this holding circuit, the relay R530 fully operates to open, at RA534, the holding circuit for the relay R540 and the operating circuit for the relay R550, causing both of these relays to restore. At 35 RA535, the relay R530 opens a point in its own operating circuit and at RA536 it disconnects the start conductor C336 from ground. At RA533, the relay R530 opens a point in the previously traced circuit for energizing the upper winding 40 of R540 in series with the signal lamp 204. At RA532, the relay R530 completes a multiple path for impressing ground potential upon the control conductor 37 of the trunk line 36. At RA531, the relay R530 opens a point in the above-traced 45 path for transmitting ring-back tone current over the calling loop circuit to the calling substation. At RA534, the relay R530 also opens a point in the above-traced circuit for energizing the lower winding of the relay R240, causing the 50 last-named relay and the relay R270 sequentially to restore in an obvious manner. Following the operation of the relay R530 and the restoration of the relays R540, R550, R240 and R270, no further operation of the apparatus shown in Fig. 55 5 occurs until the connection is released at the calling substation A. In this regard, it will be noted that the apparatus shown in Fig. 5 is effectively locked out of service although the apparatus shown in Fig. 2 is free to be used in 60 routing other calls to the operator's position 200. When the connection is thereafter cleared out at the calling substation, the relays R500 and R510 are caused to restore in the exact manner pointed out above, the relay R510 functioning 65 to open at RA514 the holding circuit for the relay R530 causing the last-named relay to restore. Thus, the apparatus illustrated in Fig. 5 is fully released.

In the event the call is answered at the operator's position 200 and the calling subscriber hangs up before the operator restores the key 201 to normal, the relay R530 is not caused to operate. Thus, when the relays R500 and R510 sequentially restore in response to interruption 70 75

of the calling loop circuit, the relays R540 and R550 are caused to release in the manner described above. Upon restoring, the relay R500 also functions to open at RA502 a point in the

5 above-traced operating circuit for the relay R530. Accordingly, when the operator restores the key 201 to normal the resulting release of the relay R250 is ineffective to complete the operating circuit for the relay R530. When the 10 operator restores the answer key 201 to its normal position, the relays R250, R260, R240 and R270 are caused sequentially to restore in the manner previously explained.

In the foregoing explanation with reference to 15 the call routed to the line 11 and intercepted through operation of the line relay R220, it is pointed out that the relay R230 operates in response to the complete operation of this line relay. It is also pointed out that the relay R230 20 is arranged to respond to the operation of any of the other line relays individually associated with the multiparty subscribers' lines. Upon operating, the relay R230 functions to prepare a path for short-circuiting the upper winding of 25 the relay R540. In the event a call is intercepted through operation of the apparatus shown in Fig. 5 during an interval when one of the indicated line relays is operated, this short-circuiting path is completed. Specifically, this 30 path extends from ground at RA514 by way of the upper winding of R540, RA543, RA512, RA533, C287, RA278, and RA235 back to ground. When this path is completed, the relay R540 is prevented from operating to extend the intercepted call to the operator's position. Accordingly, ring-back tone current is conducted to the 35 calling loop circuit over the previously traced path including the condenser 516, RA511, RA531 and RA542. When the call is thereafter answered at the operator's position, the relay R270 40 operates to open, at RA278, the short circuiting path just traced and a point in the previously traced operating circuit for the relay R540. Accordingly, it will be seen that the call first routed 45 through the trunk circuit apparatus of Fig. 2 to the operator's position 200 is guarded against intrusion occasioned by a second call intercepted through operation of the apparatus shown in Fig. 5. When, however, the apparatus of Fig. 2 50 is subsequently released the waiting call as routed to the apparatus of Fig. 5 is extended to the operator's position 200 in the exact manner previously described.

While there has been described what is at 55 present considered to be the preferred embodiment of the invention, it will be understood that various modifications may be made therein, and it is intended to cover in the appended claims all such modifications as fall within the true spirit 60 and scope of the invention.

What is claimed is:

1. In an automatic telephone system, an operator's position, a plurality of subscribers' lines including at least one multiparty line adapted to have a plurality of substations associated therewith, automatic switching apparatus for establishing connections between said lines, said automatic switching apparatus including a selector switch comprising at least one set of inactive 65 contacts adapted to be connected to an outgoing trunk line, means responsive to a call routed from a calling one of said subscribers' lines through said automatic switching apparatus to said set of inactive contacts for extending a connection from the calling line to said operator's

position, and means responsive to a call intended for one of said substations for extending a connection from the calling line to said operator's position.

2. In an automatic telephone system, an operator's position, a plurality of subscribers' lines including at least one multiparty line adapted to have a plurality of substations associated therewith, automatic switching apparatus for establishing connections between said lines, said automatic switching apparatus including a selector switch comprising at least one level of inactive contacts, said contacts being arranged in sets and each set being adapted to be connected to a trunk line outgoing from said selector switch, means responsive to a call routed from a calling one of said subscribers' lines through said automatic switching apparatus to the first set of inactive contacts in said contact level for extending a connection from the calling line to said operator's position, and means responsive to a call intended for one of said substations for extending a connection from the calling line to said operator's position. 15

3. In an automatic telephone system, an operator's position, line connecting apparatus associated with said operator's position, a plurality of subscribers' lines including at least one multiparty line adapted to have a plurality of substations associated therewith, automatic switching apparatus for establishing connections between said lines, said automatic switching apparatus including a selector switch comprising at least one set of inactive contacts adapted to be connected to a trunk line outgoing from said switch, means responsive to a call routed from a calling one of said subscribers' lines through said automatic switching apparatus to said set of inactive contacts for extending a connection from the calling line by way of said line connecting apparatus to said operator's position, and means responsive to a call intended for one of said substations for extending a connection from the calling line by way of said line connecting apparatus to said operator's position. 20

4. In an automatic telephone system, an operator's position, signaling means at said operator's position, a plurality of subscribers' lines including at least one multiparty line adapted to have a plurality of substations associated therewith, automatic switching apparatus for establishing connections between said lines, said automatic switching apparatus including a selector switch comprising at least one set of inactive contacts adapted to be connected to a trunk line outgoing from said switch, means responsive to a call routed from a calling one of said subscribers' lines through said automatic switching apparatus to said set of inactive contacts for extending a connection from the calling line by way of said line connecting apparatus to said operator's position, and means responsive to a call intended for one of said substations for extending a connection from the calling line by way of said line connecting apparatus to said operator's position. 25

5. In an automatic telephone system, an operator's position, signaling means at said operator's position, a plurality of subscribers' lines including at least one multiparty line adapted to have a plurality of substations associated therewith, automatic switching apparatus for establishing connections between said lines, said automatic switching apparatus including a selector switch comprising at least one set of inactive contacts adapted to be connected to a trunk line outgoing from said switch, means responsive to a call routed from a calling one of said subscribers' lines through said automatic switching apparatus to said set of inactive contacts for extending a connection from the calling line to said operator's position and for causing said signaling means to operate and produce a signal of one character, and means responsive to a call intended for one of said substations for extending a connection from the calling line to said operator's position, and for causing said signaling means to operate and produce a signal of a different character. 30

6. In an automatic telephone system, an operator's position, a signal device at said operator's position, an operating circuit for said signal device, a plurality of subscribers' lines including at least one multiparty line adapted to have a plurality of substations associated ther- 35

- with, automatic switching apparatus for establishing connections between said lines, said automatic switching apparatus including a selector switch comprising at least one set of inactive contacts adapted to be connected to a trunk line outgoing from said switch, means responsive to a call routed from a calling one of said subscribers' lines through said automatic switching apparatus to said set of inactive contacts for extending a connection from the calling line to said operator's position and for completing said operating circuit. 5
6. In an automatic telephone system, an operator's position, a plurality of subscribers' lines including at least one multiparty line adapted to have a plurality of substations associated therewith, automatic switching apparatus for establishing connections between said lines, said automatic switching apparatus including a selector switch comprising at least one set of inactive contacts adapted to be connected to a trunk line outgoing from said switch, means responsive to a call routed from a calling one of said subscribers' lines through said automatic switching apparatus to said set of inactive contacts for extending a connection from the calling line to said operator's position and for completing said operating circuit. 10
7. In an automatic telephone system, an operator's position, a plurality of subscribers' lines including at least one multiparty line adapted to have a plurality of substations associated therewith, automatic switching apparatus for establishing connections between said lines, said automatic switching apparatus including a selector switch comprising at least one set of inactive contacts adapted to be connected to a trunk line outgoing from said switch, means responsive to a call intended for one of said substations for extending a connection from the calling line to said operator's position and for rendering said first-named means ineffective to extend a call to said operator's position. 15
8. In an automatic telephone system, an operator's position, a plurality of subscribers' lines including at least one multiparty line adapted to have a plurality of substations associated therewith, automatic switching apparatus for establishing connections between said lines, said automatic switching apparatus including a selector switch comprising at least one set of inactive contacts adapted to be connected to a trunk line outgoing from said switch, means responsive to a call intended for one of said substations for extending a connection from the calling line to said operator's position and for rendering said first-named means inoperative to extend a connection to said operator's position. 20
9. In an automatic telephone system, an operator's position, line connecting apparatus associated with said operator's position, a plurality of subscribers' lines including at least one multiparty line adapted to have a plurality of substations associated therewith, automatic switching apparatus for establishing connections between said lines, said automatic switching apparatus including a selector switch comprising at least one set of inactive contacts adapted to be connected to a trunk line outgoing from said switch, a first relay associated with said multiparty line and operative to connect said multiparty line to said line connecting apparatus, thereby to extend a connection from said multiparty line to said operator's position, an operating circuit for said relay, means operative to energize said operating circuit when a call intended for one of said substations is routed from a calling one of said subscribers' lines through said automatic switching apparatus to said multiparty line, and means responsive to a call routed from a calling one of said subscribers' lines through said automatic switching apparatus to said set of inactive contacts for extending a connection from the calling line by way of said line connecting apparatus to said operator's position and for interrupting said operating circuit. 25
10. In an automatic telephone system, an operator's position, line connecting apparatus associated with said operator's position, a plurality of subscribers' lines including at least one multiparty line adapted to have a plurality of substations associated therewith, automatic switching apparatus for establishing connections between said lines, said automatic switching apparatus including a selector switch comprising at least one set of inactive contacts adapted to be connected to a trunk line outgoing from said switch, a first relay operative to complete a connection between said set of inactive contacts and said line connecting apparatus, thereby to extend a connection from said set of inactive contacts to said operator's position, an operating circuit for said relay, means responsive to a call routed from a calling one of said subscribers' lines through said automatic switching apparatus to said set of inactive contacts for completing said operating circuit, and means responsive to a call intended for one of said substations for extending a connection from the calling line by way of said line connecting apparatus to said operator's position and for interrupting said operating circuit. 30
11. In an automatic telephone system, an operator's position, line connecting apparatus associated with said operator's position, a plurality of subscribers' lines including at least one multiparty line adapted to have a plurality of substations associated therewith, automatic switching apparatus for establishing connections between said lines, said automatic switching apparatus including a selector switch comprising at least one set of inactive contacts adapted to be connected to a trunk line outgoing from said switch, a first relay associated with said multiparty line and operative to connect said multiparty line to said line connecting apparatus, thereby to extend a connection from said multiparty line to said operator's position, an operating circuit for said first relay, means operative to energize said operating circuit when a call intended for one of said substations is routed from a calling one of said subscribers' lines through said automatic switching apparatus to said multiparty line, and means responsive to a call intended for one of said substations for extending a connection from the calling line by way of said line connecting apparatus to said operator's position and for interrupting said operating circuit. 35

intended for one of said substations is routed from a calling one of said subscribers' lines through said automatic switching apparatus to said multiparty line, a second relay operative to complete a connection between said set of inactive contacts and said line connecting apparatus, thereby to extend a connection from said set of inactive contacts to said operator's position, a second operating circuit for said second relay, means responsive to a call routed from a calling one of said subscribers' lines through said automatic switching apparatus to said set of inactive contacts for completing said second operating circuit, means responsive to the operation of said second relay for interrupting said first-named operating circuit, and means responsive to the operation of said first relay for interrupting said second operating circuit.

12. In an automatic telephone system, an operator's position, line connecting apparatus associated with said operator's position, a signal device at said operator's position, a plurality of subscribers' lines including at least one multi-party line adapted to have a plurality of substations associated therewith, automatic switching apparatus for establishing connections between said lines, said automatic switching apparatus including a selector switch comprising at least one set of inactive contacts adapted to be connected to a trunk line outgoing from said switch, a relay operative to complete a connection between said set of inactive contacts and said line connecting apparatus, thereby to extend a connection from said set of inactive contacts to said operator's position, a circuit for energizing said relay and said signal device in series, means responsive to a call routed from a calling one of said subscribers' lines through said automatic switching apparatus to said set of inactive contacts for completing said circuit, and means responsive to a call intended for one of said substations for extending a connection from the calling line by way of said line connecting apparatus to said operator's position.

45 13. In an automatic telephone system, an operator's position, line connecting apparatus associated with said operator's position, a signaling device at said operator's position, a plurality of subscribers' lines including at least one multi-party line adapted to have a plurality of substations associated therewith, automatic switching apparatus for establishing connections between said lines, said automatic switching apparatus including a selector switch comprising at least 50 one set of inactive contact adapted to be connected to a trunk line outgoing from said switch, means responsive to a call routed from a calling one of said subscribers' lines through said automatic switching apparatus to said set of inactive 55 contacts for extending a connection from the calling line by way of said line connecting apparatus to said operator's position and for causing the operation of said signaling device to produce a signal of one character, means responsive to a 60 call intended for one of said substations for extending a connection from the calling line by way of said line connecting apparatus to said operator's position and for causing said signaling device to produce a signal of a different character, means responsive to the operation of said 65 first-named means for rendering said second-named means inoperative to extend a connection to said operator's position, and means responsive to operation of said second-named 70 means for rendering said first-named means in- 75

operative to extend a connection to said operator's position.

14. In an automatic telephone system, an operator's position, line connecting apparatus associated with said operator's position, a signaling device at said operator's position, a plurality of subscribers' lines including at least one multiparty line adapted to have a plurality of substations associated therewith, automatic switching apparatus for establishing connections between said lines, said automatic switching apparatus including a selector switch comprising at least one set of inactive contacts adapted to be connected to a trunk line outgoing from said switch, a relay associated with said multiparty line and operative to connect said multiparty line to said line connecting apparatus, thereby to extend a connection from said multiparty line to said operator's position, an operating circuit for said relay, means operative to energize said operating circuit when a call intended for one of said substations is routed from a calling one of said subscribers' lines through said automatic switching apparatus to said multiparty line, means responsive to the operation of said relay for causing the operation of said signaling device to produce a signal of one character, means responsive to a call routed from a calling one of said subscribers' lines through said automatic switching apparatus to said inactive set of contacts for extending a connection from the calling line by way of said line connecting apparatus to said operator's position, and means responsive to the operation of said last-named means for interrupting said operating circuit and for causing the operation of said signaling device to produce a signal of a different character.

15. In an automatic telephone system, an operator's position, line connecting apparatus associated with said operator's position, a signaling device at said operator's position, a plurality of subscribers' lines including at least one multi-party line adapted to have a plurality of substations associated therewith, automatic switching apparatus for establishing connections between said lines, said automatic switching apparatus including a selector switch comprising at least one set of inactive contacts adapted to be connected to a trunk line outgoing from said switch, a relay operative to complete a connection between said set of inactive contacts and said line connecting apparatus, thereby to extend a connection from said set of inactive contacts to said operator's position, an operating circuit for said relay, means responsive to a call routed from a calling one of said subscribers' lines through said automatic switching apparatus to said set of inactive contacts for completing said circuit and for causing the operation of said signaling device to produce a signal of one character, means responsive to a call intended for one of said substations for extending a connection from the calling line by way of said line connecting apparatus to said operator's position, and means operative in response to operation of said last-named means for interrupting said operating circuit and for causing the operation of said signaling device to produce a signal of a different character.

16. In an automatic telephone system, an operator's position, line connecting apparatus associated with said operator's position, a signaling device at said operator's position, a plurality of subscribers' lines including at least one multi-party line adapted to have a plurality of substations 75

5 tions associated therewith, automatic switching apparatus for establishing connections between said lines, said automatic switching apparatus including a selector switch comprising at least one set of inactive contacts adapted to be connected to a trunk line outgoing from said switch, a first relay associated with said multiparty line and operative to connect said multiparty line to said line connecting apparatus, thereby to extend a connection from said multiparty line to said operator's position, an operating circuit for said relay, means operative to energize said operating circuit when a call intended for one of said substations is routed from a calling one of said subscribers' lines through said automatic switching apparatus to said multiparty line, means responsive to the operation of said relay for causing the operation of said signaling device to produce a signal of one character, a second relay operative to complete a connection between said set of inactive contacts and said line connecting apparatus, thereby to extend a connection from said set of inactive contacts to said operator's position, a second operating circuit for said second relay, means responsive to a call routed from a calling one of said subscribers' lines through said automatic switching apparatus to said set of inactive contacts for completing said second operating circuit, means responsive to the operation of said second relay for interrupting said first-named operating circuit and for causing the operation of said signaling device to produce a signal of a different character, and means responsive to operation of said first-named relay for interrupting said second operating circuit.

10 17. In an automatic telephone system, an operator's position, a plurality of subscribers' lines including a pair of multiparty subscribers' lines each adapted to have a plurality of substations associated therewith, automatic switching apparatus for establishing connections between said lines, said automatic switching apparatus including a selector switch comprising at least one set of inactive contacts adapted to be connected to a trunk line outgoing from said switch, means responsive to a call routed from a calling one of said subscribers' lines through said automatic switching apparatus to said set of inactive contacts for extending a connection from the calling line to said operator's position, line relays individually associated with said pair of lines, each of said relays being operative to extend a connection from its associated line to said operator's position, means responsive to a call routed from a calling one of said subscribers' lines through said automatic switching apparatus to one of said multiparty lines for causing the operation of the relay associated with said one multiparty line, and means responsive to the operation of said last-named relay for preventing the other of said relays from operating.

15 18. In an automatic telephone system, an operator's position, a plurality of subscribers' lines including a pair of multiparty subscribers' lines each adapted to have a plurality of substations associated therewith, automatic switching apparatus for establishing connections between said lines, said automatic switching apparatus including a selector switch comprising at least one set of inactive contacts adapted to be connected to a trunk line outgoing from said switch, means responsive to a call routed from a calling one of said subscribers' lines through said automatic switching apparatus to said set of inactive contacts for extending a connection from the calling

20 line to said operator's position, line relays individually associated with said pair of lines, each of said relays being operative to extend a connection from its associated line to said operator's position, means responsive to a call routed from a calling one of said subscribers' lines through said automatic switching apparatus to one of said multiparty lines for causing the operation of the relay associated with said one multiparty line, and means responsive to the operation of said last-named means for preventing said first-named means and the other of said relays from operating.

25 19. In an automatic telephone system, an operator's position, a plurality of subscribers' lines including a pair of multiparty subscribers' lines each adapted to have a plurality of substations associated therewith, automatic switching apparatus for establishing connections between said lines, said automatic switching apparatus including a selector switch comprising at least one set of inactive contacts adapted to be connected to a trunk line outgoing from said switch, means responsive to a call routed from a calling one of said subscribers' lines through said automatic switching apparatus to said set of inactive contacts for extending a connection from the calling line to said operator's position, line relays individually associated with said pair of lines, each of said relays being operative to extend a connection from its associated line to said operator's position, means responsive to a call routed from a calling one of said subscribers' lines through said automatic switching apparatus to one of said multiparty lines for causing the operation of the relay associated with said one multiparty line, and means responsive to the operation of said first-named means for preventing either of said relays from operating.

30 20. In an automatic telephone system, an operator's position, a plurality of subscribers' lines including a pair of multiparty subscribers' lines each adapted to have a plurality of substations associated therewith, automatic switching apparatus for establishing connections between said lines, said automatic switching apparatus including a selector switch comprising at least one set of inactive contacts adapted to be connected to a trunk line outgoing from said switch, means responsive to a call routed from a calling one of said subscribers' lines through said automatic switching apparatus to said set of inactive contacts for extending a connection from the calling line to said operator's position, line relays individually associated with said pair of lines, each of said relays being operative to extend a connection from its associated line to said operator's position, means responsive to a call routed from a calling one of said subscribers' lines through said automatic switching apparatus to one of said multiparty lines for causing the operation of the relay associated with said one multiparty line, and means responsive to the operation of said first-named means for preventing either of said relays from operating.

35 21. In an automatic telephone system, an operator's position, line connecting apparatus associated with said operator's position, a plurality of subscribers' lines including a pair of multiparty subscribers' lines each adapted to have a plurality of substations associated therewith,

- automatic switching apparatus for establishing connections between said lines, said automatic switching apparatus including a selector switch comprising at least one set of inactive contacts 5 adapted to be connected to a trunk line outgoing from said switch, means responsive to a call routed from a calling one of said subscribers' lines through said automatic switching apparatus to said inactive contacts for extending a connection from the calling line by way of said line connecting apparatus to said operator's position, line relays individually associated with said pair of lines, each of said relays being operative to extend a connection from its associated line by 10 way of said line connecting apparatus to said operator's position, means responsive to a call routed from a calling one of said subscribers' lines through said automatic switching apparatus to one of said multiparty lines for causing the operation of the relay associated with said one multiparty line, and means responsive to the operation of said last-named relay for preventing the other of said relays from operating.
22. In an automatic telephone system, a subscriber's line adapted to have a plurality of substations associated therewith, apparatus for providing ringing currents individually corresponding to said substations, an operator's position, means responsive to ringing current projected over said line for routing a call intended for one of said substations to said operator's position, means including a reverting call switch for projecting over said line ringing currents corresponding to both the calling and called substations when a reverting call is initiated on said line, and means for preventing said first-named means from responding to the ringing current corresponding to the calling substation.
23. In an automatic telephone system, a plurality of subscribers' lines including a multiparty line adapted to have a plurality of substations associated therewith, automatic switching apparatus operative to establish connections between said lines, an operator's position, means responsive to a call routed from one of said lines through said automatic switching apparatus to said multiparty line and intended for one of said substations for extending a connection from the calling line to said operator's position, and means for preventing the operation of said first-named means during the operation of said automatic switching apparatus to complete a reverting call connection between two of said substations.
24. In an automatic telephone system, a plurality of subscribers' lines including a multiparty line adapted to have a plurality of substations associated therewith, ringing apparatus for providing ringing currents individually corresponding to said substations, automatic switching apparatus operative to establish connections between said lines and including means for connecting said ringing apparatus to project ringing current over called ones of said lines, an operator's position, means responsive to ringing current projected over said multiparty line during the extension of a call routed from one of said lines through said automatic switching apparatus to said multiparty line and intended for one of said substations for routing said call to said operator's position, means including a reverting call switch for projecting over said multiparty line ringing current corresponding to both the calling and called substations when a reverting call is initiated on said multiparty line, and

mean for preventing said second-named means from responding to the ringing current corresponding to the calling substation.

25. In an automatic telephone system, a subscriber's line adapted to have a plurality of substations associated therewith, ringing apparatus including means for providing ringing voltages individually corresponding to said substations, an automatic switch having access to said line and including means for selectively impressing said ringing voltages upon said line, a device connected to be energized by ringing voltage impressed upon said line, an operator's position, means controlled by said device for extending to said operator's position a connection routed through said switch to said line, a reverting call switch operative to impress on said line the voltages corresponding to both the calling and called substations when a reverting call is initiated on said line, and means for preventing said last-named means from responding to ringing voltage impressed on said line by said reverting call switch.

26. In an automatic telephone system, a subscriber's line adapted to have a plurality of substations associated therewith, ringing apparatus including means for impressing ringing voltage on said line during any one of a plurality of time intervals, a device controlled by said ringing apparatus and operative only during one of said intervals, an automatic switch having access to said line and including means for selecting the ringing interval during which ringing current is projected over said line from said ringing apparatus, an operator's position, means controlled by said device for extending to said operator's position a connection routed through said switch to said line only in the event the selected ringing interval at least partially overlaps said one interval, a reverting call switch operative to impress ringing voltage on said line during each of at least two of said intervals when a reverting call is initiated on said line, and means for controlling said device and said reverting call switch to prevent ringing voltage from being impressed on said line by said reverting call switch during any period when said device is operated.

27. In an automatic telephone system, a subscriber's line adapted to have a plurality of substations associated therewith, ringing apparatus including means for impressing ringing voltage on said line during any one of a plurality of ringing intervals, a device, means controlled by said ringing apparatus for causing the operation of said device during only one portion of one of said intervals, an automatic switch having access to said line and including means for selecting the ringing interval during which ringing current is projected over said line from said ringing apparatus, an operator's position, means controlled by said device for extending to said operator's position a connection routed through said switch to said line only in the event the selected ringing interval overlaps said one portion of said one interval, a reverting call switch operative to impress ringing voltage on said line during each of at least two of said intervals when a reverting call is initiated on said line, and means controlled by said ringing apparatus for preventing ringing voltage from being impressed on said line during said one portion of said one interval.

28. In an automatic telephone system, a subscriber's line adapted to have a plurality of substations associated therewith, ringing apparatus including means for impressing ringing voltage

on said line during any one of a plurality of ringing intervals, a device, means controlled by said ringing apparatus for causing the operation of said device during only one portion of one of said intervals, an automatic switch having access to said line and including means for selecting the ringing interval during which ringing current is projected over said line from said ringing apparatus, an operator's position, means controlled by said device for extending to said operator's position a connection routed through said switch to said line only in the event the selected ringing interval overlaps said one portion of said one interval, and a reverting call switch including means operative to impress ringing voltage on said line only during another portion of said one interval.

29. In an automatic telephone system, a subscriber's line adapted to have a plurality of substations associated therewith, ringing apparatus including means for impressing ringing voltage on said line during any one of a plurality of ringing intervals, a plurality of devices individually corresponding to different ones of said ringing intervals, cyclically operating means controlled by said ringing apparatus for controlling said devices to cause the operation thereof during only portions of the intervals respectively corresponding thereto, an automatic switch having access to said line and including means for selecting the ringing interval during which ringing current is projected over said line from said ringing apparatus, means controlled by a predetermined one of said devices for extending to said operator's position a connection routed through said switch to said line only in the event the selected ringing interval overlaps the period during which said predetermined one of said devices is operated, and a reverting call switch including means controlled by said cyclically operating means for impressing ringing voltage on said line during the portion of each of said ringing intervals when the corresponding one of said devices is not operated.

30. In an automatic telephone system, a subscriber's line adapted to have a plurality of substations associated therewith, ringing apparatus including means for impressing ringing voltage on said line during any one of a plurality of ringing intervals, a plurality of devices individually corresponding to said intervals, a plurality of sets of relays controlled by said ringing apparatus and individually corresponding to said intervals, each of said sets of relays being operative to divide the corresponding ringing interval into two periods and to cause the operation of the associated one of said devices during one of said periods, an automatic switch having access to said line and including means for selecting the ringing interval during which ringing voltage is impressed on said line from said ringing apparatus, an operator's position, means controlled by one of said devices for extending to said operator's position a connection routed through said switch to said line only in the event the selected ringing interval overlaps the period during which said one device is operated, and a reverting call switch including means controlled by said relays for impressing ringing voltage on said line during the period of each ringing interval when the corresponding one of said devices is not operated.

31. In an automatic telephone system, a subscriber's line adapted to have a plurality of substations associated therewith, cyclically operating ringing apparatus including means for pro-

viding ringing voltages of different frequencies during successive intervals of each ringing cycle, said frequencies individually corresponding to said substations, a plurality of devices individually corresponding to said intervals, a plurality of sets of relays controlled by said ringing apparatus and individually corresponding to said intervals, each of said sets of relays being operative to divide the corresponding ringing interval into two periods and to cause the operation of the associated one of said devices during one of said periods, an automatic switch having access to said line and including means for selecting the ringing interval during which ringing voltage is impressed on said line from said ringing apparatus, an operator's position, means controlled by one of said devices for extending to said operator's position a connection routed through said switch to said line only in the event the selected ringing interval overlaps the period during which said one device is operated, a reverting call switch including means for selecting the ringing voltages having frequencies corresponding to calling and called ones of said substations, and means controlled by said relays for impressing the selected voltages alternately on said line during the periods of said ringing intervals when said devices are not operated.

32. In an automatic telephone system, a line adapted to have a plurality of substations associated therewith, ringing apparatus including means for impressing ringing voltage on said line during any one of a plurality of ringing intervals, an automatic switch having access to said line and including means for selecting the ringing interval during which ringing voltage is impressed on said line by said ringing apparatus, and a reverting call switch including means controlled by said ringing apparatus for impressing ringing voltage on said line only during a predetermined part of each ringing interval.

33. In an automatic telephone system, a line adapted to have a plurality of substations associated therewith, cyclically operating ringing apparatus including means for providing ringing voltages of different frequencies during successive intervals of each ringing cycle, an automatic switch having access to said line and including means for selecting the ringing interval during which ringing voltage is to be impressed on said line by said ringing apparatus, a reverting call switch including means for selecting the ringing voltages having frequencies corresponding to calling and called ones of said substations, and means controlled by said ringing apparatus for impressing the selected voltages alternately on said line only during predetermined parts of alternate ones of said intervals.

34. In an automatic telephone system, a line adapted to have a plurality of substations associated therewith, cyclically operating ringing apparatus including means for providing ringing voltages of different frequencies during successive intervals of each ringing cycle, a plurality of sets of relays controlled by said ringing apparatus and individually corresponding to said intervals, each of said sets of relays being operative to divide each corresponding ringing interval into first and second periods, an automatic switch having access to said line and including means for selecting the ringing interval of each ringing cycle during which ringing voltage is to be impressed on said line by said ringing apparatus, a reverting call switch including means for selecting the ringing voltages having frequencies

- corresponding to calling and called ones of said substations, and means controlled by said relays for impressing the selected voltages alternately on said line only during the respective second 5 periods of said ringing intervals.
35. In an automatic telephone system, a subscriber's line adapted to have a plurality of substations associated therewith, apparatus for providing ringing currents individually corresponding 10 to said substations, an operator's position, means responsive to ringing current projected over said line for routing a call intended for one of said substations to said operator's position, means for preventing said first-named 15 means from responding to transient voltages impressed on said line, means including a reverting call switch for projecting over said line ringing currents corresponding to both the calling and called substations when a reverting call is initiated on said line, and means for preventing said first-named means from responding to the ringing current corresponding to the calling 20 station.
36. In an automatic telephone system, a subscriber's line adapted to have a plurality of substations associated therewith, ringing apparatus including means for providing ringing voltages individually corresponding to said substations, an automatic switch having access to said line and 25 including means for selectively impressing said ringing voltages upon said line, a device controlled by said ringing apparatus and operative when ringing voltage is impressed upon said line, an operator's position, means controlled by said 30 device and including a relay adapted to be energized by ringing voltage impressed on said line for extending to said operator's position a connection routed through said switch to said line, means for preventing said relay from responding 35 to transient voltages impressed on said line, a reverting call switch including means for impressing on said line the voltages corresponding to both the calling and called substations when a reverting call is initiated on said line, and means 40 for preventing said relay from responding to ringing voltage impressed on said line by said reverting call switch.
37. In a telephone system, a subscriber's line, apparatus for projecting ringing current over 45 said line, an operator's position, means responsive to ringing current projected over said line for extending a connection to said operator's position, and means for preventing said first-named means from responding to transient voltages 50 impressed on said line.
38. In an automatic telephone system, a subscriber's line adapted to have a plurality of substations associated therewith, apparatus for providing ringing currents individually corresponding 55 to said substations, an operator's position, means responsive to ringing current projected over said line for routing a call intended for one

of said substations to said operator's position, and means for preventing said first-named means from responding to transient voltages impressed on said line.

39. In an automatic telephone system, an operator's position, a plurality of subscriber's lines, automatic switching apparatus for establishing connections between said lines, said automatic switching apparatus including a selector switch comprising at least one set of inactive contacts 10 adapted to be connected to an outgoing line, means responsive to a call routed from a calling one of said subscribers' lines to said set of inactive contacts for extending a connection from the calling line to said operator's position, and means 15 responsive to a call intended for one of said subscribers' lines for extending a connection from the calling line to said operator's position.

40. In an automatic telephone system including a line arranged for call interception and a selector switch having at least one set of inactive contacts, apparatus for routing calls to an operator's position and arranged to respond to calls routed to said inactive contacts and to calls routed to said line. 25

41. In apparatus according to claim 40 circuit arrangements whereby said apparatus is prevented from responding to more than one call at a time.

42. In apparatus according to claim 40 circuit 30 arrangements whereby a predetermined signal is produced at said operator's position on calls routed to said inactive contacts and a different signal is produced at said operator's position on calls routed to said line. 35

43. In an automatic telephone system including ringing apparatus for providing ringing currents of different station selecting characteristics during different time intervals and a reverting call switch for selecting the ringing currents corresponding to calling and called substations in establishing reverting call connections, circuit apparatus for dividing each ringing interval into two periods and for controlling the apparatus of said reverting call switch to project selected ringing currents over calling lines only during corresponding ones of said periods. 40 45

44. In an automatic telephone system, the combination with apparatus according to claim 43, apparatus for intercepting calls intended for 50 one of the lines of the system and for routing the intercepted calls to an operator's position, said apparatus being controlled by said circuit apparatus during the other periods of said ringing intervals. 55

45. In a telephone system including a line, apparatus for intercepting calls routed to said line and for routing said calls to an operator's position, said apparatus being so connected and arranged that it does not respond to electrical 60 transients impressed on said line.

FRANK KESSLER.
